UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,393,728.

Specification of Letters Patent.

Patented Oct. 11, 1921.

Application filed December 8, 1919. Serial No. 343,284.

To all whom it may concern:

Be it known that I, SAMUEL B. WILLIAMS, Jr., a citizen of the United States, residing at Brooklyn, in the county of Kings, State 5 of New York, have invented certain new and useful Improvements in Telephone-Exchange Systems, of which the following is a full, clear, concise, and exact description.

This invention relates to telephone exchange systems and more particularly to systems of the type employing automatic switches for establishing talking connections between subscribers' lines.

Telephone exchange systems whether of 15 the full automatic or semi-automatic type may be briefly considered as consisting of two distinct classes, so far as concerns the method in which the preliminary switching operations involved in the establishment of 20 a connection are effected automatically as a result of the usual act of removing the receiver from the switchhook upon the initiation of a call. In systems of one of these classes it is the practice to have the telephone line of each subscriber to an exchange terminate in a line or individual switch. These switches are arranged to have access 25 to trunk circuits leading to a plurality of selector switches and may be controlled by 30 automatic devices in such manner that the individual switch of each line when not in use is constantly maintained in operative relation to a trunk which leads to an idle selector switch. When a subscriber, desiring 35 to connect his line with the line of some other subscriber, removes his receiver from the hook, the line switch individual to his line, being thus prepositioned before an idle trunk, is instantaneously operated to connect 40 his line directly through to a first selector switch. The subscriber may then begin to transmit impulses immediately after initiating the call with the assurance that such impulses will be properly directed to 45 the circuit extending switching mechanism.

While systems involving the use of individual switches possess the desirable feature of immediate connection to idle trunks, and the incident insurance against impulse 50 mutilation, there is this undesirable factor to be considered, that a comparatively large number of switches is required.

In the other class of automatic switching systems, above alluded to, the subscribers' 55 lines, instead of each being provided with

an individual switch are terminated in the multiple contacts of line finder switches. These finder switches may be arranged to serve any one of a large number of calling lines. When a subscriber initiates a call, a 60 condition is placed upon his line such that a finder having access thereto is set in operation to connect with the calling line and extend the same to an idle selector switch. After the finder has completed its 65 function the calling party may then transmit impulses to selectively operate the selector switches in the proper manner. By the employment of finder switches, each serving a relatively large number of lines, 70 it is evident that a considerable saving may be realized in the necessary amount of switching mechanism. But at the same time, the saving in the number of switches made possible by the use of line finders 75 may only be had by sacrificing to some extent the desirable feature of immediate connection of calling lines to idle trunks, and there is, therefore, the liability of switches being improperly operated as a result of the 80 calling subscriber commencing to send out impulses before the finder has had time to complete its function.

With the foregoing in view, the present invention has as its general object the provision of an automatic telephone system, so constructed and arranged as to embody the advantageous features of the above described methods of switching calling lines into connection with idle trunk circuits, 90 and at the same time one which practically eliminates the undesirable features of both. More specifically the object of the invention consists in the provision of improved means, in a system in which a series of automatic switches are selectively controlled by means of a switch controlling mechanism, for quickly associating such mechanism with a calling line when a call is initiated upon 95 said line.

A feature of the invention resides in the provision of means, in a system comprising a line finder and a series of directly controlled selector switches for extending calling lines together with a switch controlling mechanism adapted to be set by the calling subscriber to control said selector switches, whereby said controlling mechanism is quickly associated with the calling line on the initiation of a call, and may 110

be set by the calling subscriber while said line finder is operating to associate the calling line with the first selector switch of the series. According to this feature of the invention the calling subscriber, by means of his sender, may partially set up the controlling mechanism during the time the line finder is finding the calling line, whereafter the continued operation of said sender serves to send impulses over the circuits of the line finder to complete the setting of the controlling mechanism.

A further feature of the invention consists in the provision of quick acting small capacity step-by-step switches, in a system of this character involving a switch controlling mechanism, whereby the mechanism is associated with a calling line without delay and before the calling subscriber commences to dial the number of the desired line, and in the provision of large capacity switches for subsequently establishing a connection with the controlling mechanism and through switches directly controlled by said mechanism to the line of a called subscriber.

A still further feature resides in the provision of a plurality of switch controlling mechanisms common to a group of subscribers' lines, each comprising a plurality of registers for registering line numbers, whereby the designation of a desired line may be registered on said registers which thereupon operate to directly control the selector switches of the system to extend the connection from the calling line to the line of the desired subscriber.

A still further feature resides in the provision of means for directly controlling the movements of the line finder switch for selecting a brush set which has access to the subgroup of lines in which the calling line is located, by the employment of a plurality of relays which normally function to control the operation of other non-directive switches with which they are associated. This feature enables the employment of a line finder switch of the same type as the selector switches which are employed for further extending the line, and without the addition of extra equipment for selecting the proper set of brushes.

Such other features as are contemplated by the present invention will become more apparent from the following description and the appended claims. The invention will now be described in connection with one specific embodiment of the genus of the invention. In the accompanying drawings:—

Figure 1 shows one line of a main group of subscribers' lines, a finder switch for making connections therewith, a district selector switch for extending a connection from a subscriber's line into a desired district of the exchange and linked to the line finder switch, together with the associated cir-

cuits and apparatus through the medium of which the switches are controlled;

Fig. 2 shows an incoming selector switch for further extending a subscriber's line, together with the associated circuits for controlling it;

Fig. 3 shows a final selector or connector switch for completing a connection to a desired subscriber's line together with the circuits and apparatus for controlling it, and one of a group of subscribers' lines to which the final selector has access;

Fig. 4 shows a primary line finder switch for making a primary connection with a subgroup of subscribers' lines together with the associated circuits for controlling it;

Fig. 5 shows the secondary line finder switch for making connections with lines extended through the circuits of the primary line finder, a finder switch for extending a connection to a selector switch controlling mechanism, a finder selector for selecting an idle pair of line finder and district selector switches, together with the associated circuit and apparatus through the medium of which the switches are controlled;

Fig. 6 shows a selector controlling mechanism or impulse register for registering impulses transmitted thereto through the operation of a calling subscriber's impulse sending dial;

Fig. 7 shows the circuits of an impulse sender which is operated in accordance with the setting of the controlling mechanism disclosed in Fig. 6; and

Fig. 8 shows diagrammatically, the manner in which the several figures of the drawing are to be arranged to illustrate as much of a complete organization as is necessary to impart an understanding of the construction and mode of operation of the system.

General description of apparatus.

A single telephone line of a main group of 450 lines is shown in Fig. 1, it being understood that there are as many groups as are necessary to accommodate the lines terminating in the exchange. The main groups of lines are preferably divided into fifteen subgroups of thirty lines each, each such subgroup being served by a group of primary line finders having a capacity of thirty lines each, and are also divided into five subgroups of ninety lines each, each subgroup of ninety lines being served by one of the brush sets of each main line finder having access thereto. It would of course be possible to slightly change the manner of subgrouping by providing primary finder switches of fifty-line capacity and by providing main line finders of 500 line capacity, whereby main line finders of standard type might be used. This would, however, slightly slow down the rapidity of line extension and would to that extent sacrifice

some of the efficiency which this system is designed to attain.

The line has associated with it at the central office, a line relay 8 and a cut-off relay 9 and, being a line in an automatic exchange, is provided with the usual sending mechanism S. The line represented as a calling line A, in Fig. 1, and the line shown as a called line B, in Fig. 3, may be lines of the same type, similarly equipped but located at different exchanges or at the same exchange. In the present instance, the line shown in Fig. 3 is illustrated as one of a group of lines terminating in a private branch exchange and for that purpose is provided with a cut-off relay 9' having high and low resistance windings for co-operation with testing circuits of the final selector switches which have access thereto. The line A, shown in Fig. 1, is illustrated as provided with multiple terminals in the banks of main line finders LF and of primary line finders PLF, and with a starting circuit leading through primary line finder starting relays of all primary line finders having access to the subgroup of lines in which the line is located, the starting relays being common to all lines of the subgroup.

The groups of lines have access to a plurality of selector controlling mechanisms or impulse registering devices through the medium of primary line finder switches PLF, secondary line finder switches SLF, and register selectors RS shown in Figs. 4 and 5. In the particular system illustrated these switches are all of the well-known step-by-step type in which a stepping pawl operates a ratchet wheel to which are connected brushes or wipers adapted to travel over the contacts of an arcuate terminal bank. These brushes or wipers are so arranged that for each step of the operating magnet, the brushes or wipers engage a corresponding set of terminals. The primary finder switches are each provided with five wipers and the secondary finder switches and register selectors are each provided with six wipers. These switches have no normal position but stop in whatever position they are placed by their respective operating magnets.

The main line finders and selector switches shown in Figs. 1, 2 and 3 are not novel in themselves and have therefore been shown merely diagrammatically. These switches are substantially like the switch illustrated and described in the patent to E. B. Craft and J. N. Reynolds No. 1,123,696, issued January 5, 1915. Each of these switches comprise a longitudinally movable shaft carrying as many sets of brushes 2 as there are groups of stationary terminals to be engaged. To move the shaft up, an extension at the lower end of the shaft is brought into engagement with a constantly rotating power roller 3 by means of an idler wheel operated

by the up-drive magnet, and to move the shaft down, the extension is brought into engagement with the power roller 4 by means of an idler wheel operated by the down-drive magnet.

Normally, the brushes of each of the sets 2 are held apart so as to clear the bank terminals associated therewith by means of a separating cam (not shown) located between the innermost brushes of the set. The brushes are tripped by means of a vertically disposed tripping spindle or rod 5 having disposed thereon a tripping finger 6 for each set of brushes. The spindle 5 is rotated into tripping position by means of a single tripping magnet. The trip rod in rotating, brings all of the trip fingers 6 into position to operate the brush controlling cams of the corresponding sets of brushes, but only the brush set which has been positioned opposite its corresponding trip finger will be affected.

Each of the switches has associated with it, a commutator 7 which comprises a number of stationary commutator segments, and a set of movable wipers carried at the top of the switch shaft 1 and co-operating with the stationary segments. This commutator serves to make and break a number of controlling circuits in the various stages of the longitudinal movement of the switch shaft.

The district selector DS is so arranged as to have three distinct upward movements, first a brush selecting movement comprising five distinct steps, second a selecting movement for moving the selected brush set over the associated terminal bank comprising two steps, and third, a hunting movement over the selected group of bank terminals. The incoming selector switch IS similarly has three movements, the group selecting movement of the selected set of brushes comprising four steps. The connector switch differs slightly in construction from the other selector switches in that provision is made for driving the switch shaft upwardly at either a high speed through the high speed power roller 10 or at a slower speed through the slow speed roller 3. The switch shaft is driven upwardly in three selective movements, first, a high speed movement for selecting a set of brushes corresponding to the group of 100 lines, in which the desired line is located; second, a high speed movement for selecting the particular subgroup of 10 lines, in which the line is located; and third, a slow speed upward movement for selecting the line in the subgroup of 10. If the desired line is one terminating in a private branch exchange, the switch may make a fourth upward movement which is a slow speed hunting movement.

The finder selector shown in Fig. 5 is also of the power-driven type and substantially like the switch shown in the patent to E. B. Craft and J. N. Reynolds hereinbefore re-

ferred to, but since only a single set of brushes is required, the brush selecting or tripping mechanism is omitted.

For controlling the circuits of the system, there are employed a number of sequence switches which are shown at different points and are designated 100, 200, 300, 500, 600 and 700 respectively. These sequence switches may be of the type disclosed in Patent No. 1,127,808, issued February 9, 1915, to Reynolds and Baldwin. Each consists of an electromagnetically controlled motor or driving mechanism and a number of associated switch springs. The switch springs associated with the sequence switch 100 are designated 101 to 122 inclusive; those associated with the sequence switch 200 are designated 201 to 213 inclusive; those associated with sequence switch 300 are designated 301 to 312 inclusive; those associated with sequence switch 500 are designated 501 to 519 inclusive; those associated with sequence switch 600 are designated 600 to 612 inclusive; and those associated with sequence switch 700 are designated 701 to 709 inclusive. To each of the contacts associated with the various sequence switch springs are applied certain numerals. These numerals, in case of the cams 101, 201, 301, 501, 601 and 701, indicate the only positions of the associated sequence switches in which these particular contacts are opened; the numerals applied to all of the other contacts of each sequence switch indicate the only positions of the particular switch in which the associated contacts are closed and when the numerals are connected by the sign + the contacts are closed continuously between the positions indicated by the numerals so connected.

The controlling mechanism disclosed in Fig. 6 comprises a plurality of step-by-step register switches each provided with a plurality of wipers arranged to be moved over associated banks of contacts, each bank of contacts, with the exception of the uppermost, comprising 10 contacts. These registers are arranged to be set in succession by impulses transmitted to their respective stepping magnets over connections extending to the line of a calling subscriber, the impulses being caused through the operation of the subscriber's calling dial.

The sending mechanism shown in Fig. 7 and associated with the controlling mechanism shown in Fig. 6 is of the usual type employing a series of 20 counting relays.

Establishment of initial connection to idle register.

The manner in which the system is organized will best be presented in connection with a description of the mode of its operation. It will be assumed that the subscriber at station A initiates a call and de-

sires to secure a connection with substation B in another exchange, the number of the desired subscriber being 45689. The removal of the receiver at substation A closes a circuit for the line relay 8 which extends over 70 the line and through the armatures and back contacts of the cut-off relay 9. Line relay 8 becomes energized and at its armature and front contact closes a circuit for the starting relay 400 common to the group of 75 primary finder switches having access to the subgroup of the calling line. Relay 400 upon energizing, closes a circuit at its outer left-hand armature and front contact for the pilot alarm device (not shown) and at 80 its inner left-hand armature and front contact, closes a circuit for relays 401 of all idle finders which extends from grounded battery, through the winding of relay 401, through the left-hand armature and back 85 contact of relay 402, through the back contact and right-hand armature of relay 403, and thence to ground at the inner left-hand armature and contact of relay 400. Relay 401, upon energizing, closes a circuit for 90 relay 403 which extends from grounded battery, through the winding of this relay, through the left-hand armature and front contact of relay 401, through the back contact and right-hand armature of relay 402, 95 and thence to ground at the inner left-hand armature and front contact of relay 400. Relay 403 thereupon establishes a locking circuit for itself over its left-hand armature and front contact and thence to the test 100 brush 404. If the bank contact upon which this brush is resting at the time, leads to a line which is not in a calling condition or is engaged in a connection, the locking circuit of relay 403 will then be completed to 105 ground at the back contact and armature of the line relay 8 of such line. Relay 401 upon energizing, also closes a locking circuit for itself through its right-hand armature and front contact, through the winding 110 of relay 402, through the back contact and lowermost armature of relay 405, and to ground at the inner left-hand armature and front contact of relay 400. Relay 402 energizes in this circuit and at its left-hand 115 armature and back contact, opens the initial energizing circuit of relay 401, and at its right-hand armature and back contact, opens the initial energizing circuit of relay 403. Relay 403, upon energizing, closes a circuit 120 through the stepping magnet 406, which circuit may be traced from grounded battery, through the winding and interrupter contacts of magnet 406, through the front contact and right-hand armature of relay 125 403, and thence to ground at the inner left-hand armature and front contact of relay 400. Magnet 406 thereupon energizes, stepping the brushes of the switch to the next set of bank terminals and interrupting 130

its own energizing circuit. If the set of bank terminals which the brushes of the switch now engage lead to a non-calling or busy line, the switch will take another step 5 and will in this manner continue to move step-by-step until the brushes engage the multiple terminals of the calling line, when the test brush 404 will find no ground potential upon the test contact of the bank which 10 it engages and the locking circuit of relay 403 will thereupon be destroyed. Relay 403, upon deenergizing, opens at its right-hand armature and front contact the circuit of the stepping magnet 406 and at its left-hand armature and back contact connects ground potential through the test brush 404 to the multiple test contacts of its bank to thereby mark the multiple test contacts of the calling line as busy for preventing other 15 primary finder switches, which have been simultaneously hunting for the terminals of the calling line, from making connection therewith. At its right-hand armature and back contact, relay 403 established a circuit 20 for the relay 412 which extends from grounded battery, through the left-hand winding of relay 412, through the front contact and left-hand armature of relay 402, through the back contact and right-hand armature of relay 403, and thence to ground at 25 the inner left-hand armature and front contact of relay 400.

At the time relay 400 energized, a circuit was also established for the starting relay 30 521 for initiating the hunting movement of a secondary finder switch SLF and of a register selector RS. This circuit may be traced from grounded battery, through the winding of relay 521 and thence to ground 35 at the front contact and outer right-hand armature of relay 400. Upon energizing, relay 521 closes a circuit extending from ground, through the lower contact of sequence switch spring 502 (1), through the 40 left-hand armature and front contact of relay 521, through the lower left-hand contact of sequence switch spring 503 (1) 45 through the right-hand armature and back contact of relay 522, through the lower left-hand contact of sequence switch spring 504 (1), through the left-hand armature and back contact of relay 523, thence to grounded battery through the winding of relay 524. Relay 524 is energized in this circuit and 50 at its left-hand armature closes a circuit for the relay 522 which extends from grounded battery, through the relay 522, through the lower left-hand contact of sequence switch spring 505 (1), through the front contact 55 and left-hand armature of relay 524, through the back contact and right-hand armature of relay 523 and thence to ground through the lower right-hand and upper left-hand contacts of sequence switch 60 spring 506 (1). Relay 522 is thereupon energized and, at its left-hand armature and front contact, closes a locking circuit for itself which extends through the lower contacts of sequence switch spring 507 (1), to the test brush 525 and thence over the bank 70 contact upon which it is then resting to ground at the back contact and outer right-hand armature of relay 400 of a primary line finder, provided such primary finder has not been placed in operation by a calling line. At 75 its right-hand armature and front contact, relay 522 establishes a circuit for the stepping magnet 526 which may be traced from grounded battery, through the winding and interrupter contacts of magnet 526, through the lower left-hand contact of sequence switch spring 508 (1), through the front contact and right-hand armature of relay 522, through the lower left-hand contact or sequence switch spring 503 (1), through the 80 front contact and left-hand armature of relay 521 and thence to ground through sequence switch spring 502 (1). Stepping magnet 526 energizes in this circuit, stepping the brushes of the switch into contact 85 with the next set of bank terminals and at its interrupter contacts opens its own circuit. If the next set of terminals leads to a primary switch which is in a non-calling condition, the relay 522 will continue in a 90 locked condition and the circuit of the stepping magnet will again be established. The switch will therefore continue to move 95 step-by-step over its bank terminals until the test brush 525 engages the test terminal 100 extending to the primary finder switch which has been started by the calling line, when no ground potential will be found on the test terminal, since the relay 400 of such switch has removed the ground potential at its outer right-hand armature and back contact. Relay 522 now becomes deenergized and at its left-hand armature and back contact connects ground potential 105 through the test brush 525 to the multiple 110 test terminals connected with the primary switch which has been seized and appearing in the banks of all secondary line finders which have access thereto for preventing seizure of the same primary finder by other 115 secondary finders. At the time relay 524 energized, it also closed a locking circuit for itself extending from grounded battery, through its winding and right-hand armature contacts, through the winding of relay 120 523, through the front contact and left-hand armature of relay 521 and thence to ground at sequence switch contact 502 (1). Relay 523 is energized in this circuit and, at its left-hand armature and back contact, opens 125 the initial energizing circuit of relay 524, and its right-hand armature and back contact, opens the initial energizing circuit of the relay 522. With the relay 523 energized and the relay 522 deenergized, a circuit is 130

now effective for driving the sequence switch 500 out of position 1 and into position 2. This circuit may be traced from grounded battery, through the magnet winding of 5 sequence switch 500, through the lower right-hand contact of sequence switch 5
springs 509 (1), through the front contact and left-hand armature of relay 523, through the lower left-hand contact of sequence switch 10 spring 504 (1), through the back contact and right-hand armature of relay 522, through the lower left-hand contact of sequence switch 5
spring 503 (1), through the front contact and left-hand armature of relay 521, and thence to ground 15 through the lower contact of sequence switch spring 502 (1).

At the time relay 521 energized a circuit was also established through the winding of 20 relay 527 for starting the hunting movement of the register selector RS. This circuit may be traced from grounded battery, through the winding of relay 527, through the back contact and right-hand armature 25 of relay 528, through the left-hand contacts of sequence switch spring 510 (1), through the back contact and left-hand armature of relay 529, through the lower left-hand contact of sequence switch spring 511 (1 and 2), 30 and thence to ground at the front contact and right-hand armature of relay 521. Relay 527, upon energizing, closes a circuit for the relay 529 which may be traced from grounded battery, through the winding of relay 529, through the lower contact 35 of sequence switch spring 512 (1 and 2), through the front contact and right-hand armature of relay 527, and thence to ground at the make-before-break left-hand armature contacts of relay 528. If the wipers of the 40 register selector RS are at this time resting upon the multiples of a busy registering or switch controlling device, a locking circuit will be established for the relay 529 which 45 extends through its winding and right-hand armature contacts, through the lower right-hand contact of sequence switch spring 513 (1 to 3), through the brush 530, and thence over the busy bank contact upon which it is 50 resting to ground at the upper left-hand contact of sequence switch spring 602 (2 to 18). Relay 527, upon energizing, also closes a locking circuit for itself extending through its winding and left-hand armature 55 contacts, through the winding of relay 528, and thence to ground at the front contact and right-hand armature of relay 521 or, if at this time the sequence switch has moved into position 2, to ground through the lower 60 contacts of sequence switch spring 511. Relay 528 energizes in this circuit and, at its left-hand armature contact, opens the initial energizing circuit of the relay 529 and, at its right-hand armature and back contact,

opens the initial energizing circuit of relay 65 527. Relay 529, upon energizing, establishes a circuit for the stepping magnet 531 which may be traced from grounded battery, through the winding and interrupter contacts of the magnet 531, through the lower 70 contacts of sequence switch spring 514, through the front contact and left-hand armature of relay 529, and thence to ground at the right-hand armature and front contact of relay 521 or, if the sequence switch 75 500 has moved to position 2, to ground at the lower right-hand contact of sequence switch spring 511.

Magnet 531, upon energizing, moves the brushes of the switch RS one step into contact with the next succeeding set of bank terminals and opens its own energizing circuit. If the bank terminals upon which the switch brushes now rest lead to a busy registering mechanism, the test brush 530 80 will again encounter ground potential upon the bank terminal upon which it rests and the locking circuit of relay 529 will be maintained and the stepping magnet 531 85 will again move the switch brushes to the next set of bank terminals. This operation continues until the test brush 530 engages a bank terminal which is not grounded at the sequence switch spring 602 of the registering mechanism to which it leads the sequence switch 600 of such idle registering mechanism being in position 1. The locking circuit of relay 529 is now open and the relay retracts its armatures. At its left-hand armature and front contact, the relay 529 90 opens the circuit of the stepping magnet 531 and, at this armature and back contact, closes a circuit for driving the sequence switch 500 out of position 2 and, under the influence of the master contact 501, into position 4. This circuit may be traced from grounded battery, through the magnet winding of sequence switch 500, through the upper left-hand contact of sequence switch spring 509 (2), through the front contact 95 and right-hand armature of relay 528, through the left-hand contacts of sequence switch spring 510, through the back contact and left-hand armature of relay 529, and thence to ground at the lower right-hand contact of sequence switch spring 511 (2). At its right-hand armature and back contact, relay 529 established, upon deenergizing, a circuit for maintaining busy ground potential upon the multiple test terminals 100 appearing in the terminal banks of switches RS, which circuit is maintained through position 3 of the sequence switch and may be traced from ground at the make contacts of the left-hand armature of relay 528, through the back contact and right-hand armature of relay 529, through the lower 105 contact of sequence switch spring 513 (1 to 110 120 125 125

3) and thence through brush 530 to the test contact of the bank upon which it is resting.

As soon as sequence switch 500 moved out of position 1, the locking circuit through relays 523 and 524 was opened at the lower contact of sequence switch spring 502 and these relays thereupon released. As soon as the sequence switch moved out of position 2, the locking circuit for relays 527 and 528 was opened at the lower contacts of sequence switch spring 511. In position 2 of sequence switch 500, a circuit is closed for relay 405 (Fig. 4) for cutting through an impulse circuit from the calling line, through the brushes of the primary line finder PLF, of the secondary line finder SLF, and of the register selector RS to the line relay 613 of the selected registering mechanism. This circuit may be traced from grounded battery, through the winding of relay 405, through the right-hand armature and front contact of relay 412, through the bank terminal 532 and the brush of the secondary finder switch which is resting thereon, and thence to ground at the right-hand contacts of sequence switch spring 503, and a locking circuit is also closed at this time over the circuit just traced and through the right-hand winding of relay 412. Relay 405, upon energizing, closes the impulse circuit previously mentioned, extending from the calling line to the selected registering mechanism which may be traced from grounded battery, through the right-hand winding of relay 613, through the contact of sequence switch spring 603, (1 to 17) through the bank contact 533, a brush of the register selector RS resting thereon, through the lower contact of sequence switch spring 515 (2 to 9), over brush 534 and the bank contact on which it is resting, through the armature and front contact immediately above the winding of relay 405, through the brush 407 of the primary line finder PLF and the bank terminal on which it is resting, thence over the calling subscriber's line loop and through the contacts of the impulse sender S at the subscriber's substation A and thence back over the bank terminal 408 of the primary line finder and the brush resting thereon, through the uppermost armature and front contact of relay 405, over the bank terminal 535, a brush of switch SLF resting thereon, through the lower contact of sequence switch spring 516 (2 to 9), through the brush 536 of switch RS and the bank terminal upon which it is resting, through the contact of sequence switch spring 604 (1 to 17), and thence to ground through the left-hand winding of relay 613. Relay 405 at its lowermost armature and back contact, opens the locking circuit through relays 401 and 402, which thereupon deenergize, and at its inner lower armature, connects battery po-

tential through the resistance 409, over brush 65 410 and the bank contact upon which it is resting to ground through the cut-off relay 9, which thereupon energizes, cutting off the line relay 8, which in turn causes the de-energization of relay 400. This battery potential is also connected to the multiple test terminals appearing in the banks of all main line finder switches LF which have access to the calling line.

Upon the closure of the impulse circuit 75 above traced, the relay 613 becomes energized and at its left-hand armature and front contact closes a circuit for the slow acting relay 614. Relay 614 energizes and, at its left-hand armature and front contact, 80 prepares a circuit for the slow acting relay 615 and, at its right-hand armature and front contact, closes a circuit extending from grounded battery through the relay 616, through the lower left-hand and upper 85 right-hand contacts of sequence switch spring 605 (1) and thence to ground at the right-hand armature of relay 614. Relay 616 is energized and at its right-hand armature and front contact, closes a locking circuit 90 for itself extending to ground at the right-hand armature and front contact of relay 614. This circuit is maintained during the sending of impulses to the registering mechanism and the control of the selector 95 switches thereby. At its left-hand armature and front contact, relay 616 closes a circuit for driving the sequence switch 600 out of position 1 and into position 2, this circuit extending from grounded battery, through the 100 magnet winding of sequence switch 600, through the right-hand contact of sequence switch spring 606 (1) and to ground at the left-hand armature of relay 616. In the second position of the sequence switch, ground 105 potential is connected to the multiple test terminals corresponding to the selected registering mechanism appearing in the banks of all register selector switches RS having access thereto, from ground at the 110 left-hand contact of sequence switch spring 602 (2 to 18). The subscriber may now begin dialing the number of the called line which he desires.

Setting the registering mechanism.

115

Under the assumption that the number of the desired line is 45689, the subscriber first sets his dial S for sending impulses corresponding to the digit 4, and upon release of 120 the dial, the circuit above traced through relay 613 is interrupted five times. It is to be noted in this connection that the dial S is provided with numerals arranged in the order 0 to 9 and that therefore one more impulse is always transmitted than indicated by the numeral dialed. Upon each interruption of the circuit, the relay 613 retracts

125

its armature, thereby closing a circuit extending through the stepping magnet of the first or district brush register member of the registering mechanism, which circuit 5 may be traced from grounded battery, through the stepping magnet 617, through the lower contact of sequence switch spring 607 (2 and 3), through the winding of slow acting relay 615, through the left-hand armature and front contact of relay 614, and thence to ground at the back contact and left-hand armature of relay 613. In response to these impulses, the stepping magnet 617 moves the wipers 618, 619 and 620 10 five steps to the fifth set of bank contacts. Relay 615 was energized in the circuit through the stepping magnet 617 and, being slow to release, remains energized during the transmission of the series of impulses. 15 Upon its initial energization, it establishes a circuit for driving the sequence switch 600 out of position 2 and into position 3, this circuit extending from grounded battery, through the magnet winding of the sequence switch, 20 through the upper right-hand contact of sequence switch spring 608 (2), and to ground at the front contact and armature of relay 615. Upon the cessation of the first series of impulses, the slow relay 615 becomes deenergized and, at its armature and back contact, closes a circuit for driving the sequence switch 600 out of position 3 and into position 4. This circuit extends through the magnet winding of the sequence switch, 25 through the upper left-hand contact of sequence switch 608 (3), and thence to ground at the back contact and armature of relay 615. 30

In response to the operation of the sending dial for the second series of impulses corresponding to the second digit 5, the relay 613 transmits a series of six impulses through the stepping magnet 621 of the second or district group register member of the registering mechanism, this circuit extending 35 from grounded battery, through the winding of magnet 621, through the upper right-hand contact of sequence switch spring 607 (4 and 5), thence through the relay 615 and over the circuit previously traced to ground at the armature and back contact of relay 613. In response to this series of impulses, the magnet 621 steps the wipers 622, 40 623 and 624 six steps into contact with the sixth set of terminals of their respective banks, and relay 615 which was energized in the stepping circuit, causes the sequence switch 600 to move into position 5 by virtue of the circuit previously traced, extending through the upper right-hand contact of sequence switch spring 608 (4). Upon cessation of the second series of impulses, relay 615 becomes deenergized and establishes a circuit, previously traced, through the upper left-hand contact of sequence switch spring 608 (5) for driving the sequence switch 600

out of position 5 and into position 6. In response to the third series of impulses corresponding to the digit 6, the stepping magnet 625 becomes energized over a circuit extending through its winding, through the upper left-hand contact of sequence switch spring 607 (6 and 7), through the winding of relay 615, and thence to ground at the back contact of relay 613, thereby stepping the wipers 626, 627, 628 and 629 of the third or hundreds register member of the registering mechanism into engagement with the seventh set of bank contacts. Relay 615 energizes in the stepping circuit of magnet 625 and, at its armature and front contact, causes the sequence switch 600 to move out of position 6 and into position 7. Upon the cessation of the third series of impulses, the relay 615 is deenergized and establishes a circuit for driving sequence switch 600 out of position 7 and into position 8. In a similar manner the stepping magnet 630 in response to the fourth digit 8 steps the wipers 631 and 632 of the fourth or tens register member of the registering mechanism nine steps. The circuit for the magnet 630 extends through the lower left-hand contact of sequence switch spring 609 (8 and 9) and thence to ground at the armature and back contact of relay 613, over the circuit previously traced. Relay 615 energizes in this circuit, thereby driving sequence switch 600 out of position 8 and into position 9. Upon the cessation of this series of impulses, relay 615 retracts its armature, thereby causing sequence switch 600 to move out of position 9 and into position 10. The last series of impulses corresponding to the digit 9 causes the stepping magnet 633 to step the brushes 634 and 635 of the fifth or units register member of the registering mechanism ten steps into contact with the tenth set of bank contacts. The circuit of magnet 633 may be traced through the lower right-hand contact of sequence switch spring 609 (10 and 11), through the winding of relay 615 and thence to ground at the back contact of relay 613. Upon the energization of relay 615, in response to this series of impulses, a circuit is established for driving sequence switch 600 out of position 10 and into position 11, and upon the deenergization of relay 615, following the cessation of this series of impulses, it establishes a circuit for driving sequence switch 600 out of position 11 and into position 12. The number of the desired line which has been dialed by the calling subscriber is now completely set up on the registering mechanism.

Selection of idle main line finder.

As soon as sequence switch 600 moved out of position 1 and into position 2, a circuit was established for the relay 529 extending from grounded battery, through the wind-

ing of the relay, through the upper contact of sequence switch spring 512 (4), through brush 537 of the register selector RS, over the bank contact upon which this brush is resting, through the upper left-hand contact of sequence switch spring 606 (2 to 12), and thence to ground at the left-hand armature and front contact of relay 616. Relay 529 energizes in this circuit closing, at its right-hand armature and front contact, a locking circuit for itself extending through the upper right-hand contact of sequence switch spring 513 (4 to 10), through brush 537 and thence to ground over the circuit previously traced. At its left-hand armature and front contact a circuit is established for driving the sequence switch 500 out of position 4 and into position 5, which circuit may be traced from grounded battery, through the magnet winding of sequence switch 500, through the lower right-hand contact of sequence switch spring 514 (1 to 4), through the front contact and left-hand armature of relay 529, and thence to ground at the lower right-hand contact of sequence switch spring 511 (4 to 18). In position 5, relay 522 again energizes over a circuit traced from grounded battery, through the winding of relay 522, and thence to ground through the left-hand contacts of sequence switch spring 506 (5). Relay 522, at its left-hand armature and front contact, closes a locking circuit for itself which is effective if the test wiper 538 is resting upon a bank terminal corresponding to a busy line finder switch LF. This circuit may be traced from grounded battery, through the winding of relay 522 and its left-hand armature and front contact, through the lower right-hand and upper left-hand contacts of sequence switch spring 507, through brush 538 and the bank terminal upon which it is resting, and thence to ground at the lower right-hand contact of sequence switch spring 102. At its right-hand armature and front contact, a circuit is closed for driving sequence switch 500 out of position 5 and into position 6, which circuit may be traced from grounded battery, through the magnet winding of sequence switch 500, through the lower right-hand contact of sequence switch spring 508 (5), through the front contact and right-hand armature of relay 522, and thence to ground at the upper contact of sequence switch spring 503 (2 to 10). In position 6, the initial energizing circuit of relay 522 is broken at the left-hand contacts of sequence switch spring 506, but under the assumption that the brushes of switch FS are standing upon the multiple terminals of a busy line finder link, the relay 522 does not deenergize. A circuit is now effective for the up-drive magnet 539, which circuit extends from grounded battery, through the winding of magnet 539, through the upper contact of sequence switch spring 508 (6), through the front contact and right-hand armature of relay 522, and thence to ground at the upper contact of sequence switch spring 503. Magnet 539, upon energizing, presses the depending portion of switch shaft 1 against the constantly rotating up-drive roller 3, thereby causing the switch shaft and brush set 2 carried thereby, to be traversed upwardly over the set of bank terminals. If the next set of bank terminals leads to another busy line finder link, the test brush 538 will encounter ground potential upon the test contact of the bank and the relay 522 will remain energized, thereby maintaining the circuit of the up-drive magnet 539. As soon as the brush 538 encounters a test contact of the bank upon which there is no ground potential, the locking circuit of relay 522 will be destroyed but relay 522 will continue to attract its armatures by reason of a second locking circuit extending through its winding, through the upper right-hand contact of sequence switch spring 505 (5 $\frac{1}{2}$ to 6), through the segment 540 of the switch commutator 7, and thence to ground through the shaft wiper 541. This second locking circuit is maintained until the brush set 2 becomes properly centered upon the set of bank terminals which it is engaging, when the shaft wiper 541 will engage an insulating portion of the segment 540 and the relay 522 will thereupon become deenergized.

Upon deenergizing, the circuit of the up-drive magnet 539 is opened at the right-hand armature and front contact of relay 522 and a circuit is established for driving the sequence switch 500 out of position 6 and into position 7, this circuit extending from grounded battery, through the magnet winding of sequence switch 500, through the lower right-hand contact of sequence switch spring 504 (6), through the back contact and right-hand armature of relay 522 and thence to ground at the upper contact of sequence switch spring 503. At its left-hand armature and back contact relay 522 connects busy ground potential through contacts of sequence switch spring 507 to the multiplied test contacts in the bank of switch FS to prevent seizure of the selected link by other switches FS.

A circuit is now established for the relay 123 Fig. 1, which may be traced from grounded battery, through the winding of relay 123, through the lower contacts of sequence switch spring 103, through the bank contact and wiper 542 of switch FS, through the upper contacts of sequence switch spring 513, through wiper 537 of the switch RS and the bank contact upon which it is resting, through the upper left-hand contact of sequence switch spring 606, and thence to ground at the front contact and left-hand

armature of relay 616. Relay 123 energizes in this circuit and at its left-hand armature and front contact closes a locking circuit for itself extending through the lower right-hand contact of sequence switch spring 103 and thence to ground over the circuit previously traced. At its right-hand armature and front contact, relay 123 closes a circuit extending through the upper right-hand contact of sequence switch spring 104 for driving the sequence switch 100 out of position 1 and into position 2.

Operation of main line finder.

15 In position 2, a circuit is established for the relay 124 extending from grounded battery, through the right-hand winding of this relay, through the lower right-hand contact of sequence switch spring 105, over a bank 20 contact of sequence FS, through brush 543, through the upper right-hand contact of sequence switch spring 504 (7), through the back contact and right-hand armature of relay 522, and thence to ground at the upper 25 contact of sequence switch spring 503. Relay 124 energizes in this circuit and at its right-hand armature and front contact establishes a circuit for the up-drive magnet 125 of the line finder switch LF, this circuit 30 extending from grounded battery, through the winding of magnet 125, through the left-hand contacts of sequence switch spring 106, and thence to ground at the front contact of relay 124. The magnet 125 is energized and 35 thereby presses the depending portion of the switch shaft 1 against the constantly rotating up-drive roller 3. The switch shaft 1, together with its brush sets 2, is thereupon driven upwardly. Upon the initial upward 40 movement of the switch shaft, the shaft wiper 126 engages the lower conducting portion of the segment 127 of the commutator 7 of the line finder LF, whereby a circuit is established for the relay 527 (Fig. 5) which 45 circuit may be traced from grounded battery, through the winding of relay 527, through the back contact and right-hand armature of relay 528, through the lower left-hand and upper right-hand contacts of 50 sequence switch spring 510, through the brush 544 of switch FS and the bank terminal upon which it is resting, through the right-hand contact of sequence switch spring 107, through the commutator segment 127 55 and the wiper 126, then in engagement therewith, through the upper left-hand contact of sequence switch spring 106, and thence to ground at the front contact and right-hand armature of relay 124. Relay 527 energizes 60 in this circuit and locks up over a circuit extending through its left-hand armature and front contact, through the winding of relay 528, and thence to ground through the lower contacts of sequence switch spring 511. Relay 65 528, however, does not energize in this

circuit since its winding is shunted by ground connection at the shaft wiper 126 of the line fiber over the circuit previously traced. If the calling subscriber's line is located in the subgroup of lines terminating in the bank to which the first, lowermost brush set of the line finder LF has access, then a circuit is established at this time for the relay 522 extending from grounded battery, through the winding of relay 522, 75 through the upper left-hand contact of sequence switch spring 505 (7), through brush 545, and thence over the bank terminal N upon which it is resting to the junction point 80 designated 1, and from the junction point through the front contact and right-hand armature of relay 527 and to ground at the left-hand armature contacts of relay 528. Relay 522 is energized in this circuit and, at its right-hand armature and back contact, 85 opens the energizing circuit of relay 124 which thereupon deenergizes and opens the circuit of the up-drive magnet 125. If, however, the calling subscriber's line is located in the fifth subgroup of lines as we will now 90 assume, the bank terminals N connected to primary line finders assigned to this subgroup would not be connected to the junction point 1 but to the junction point 5 and thereby, upon the energization of relay 527, 95 no circuit would be effective for the relay 522 and consequently the upward movement of the line finder shaft continues.

As soon as the wiper 126 engages the first insulating portion of the segment 127, the 100 shunt around relay 528 is removed and this relay energizes over the locking circuit of relay 527, thereby opening at its right-hand armature and back contact the initial energizing circuit of relay 527 and at its right-hand armature and front contact closing a circuit for the relay 524 which extends from grounded battery, through the relay 524, through the back contact and left-hand armature of relay 523, through the contacts 110 of sequence switch spring 517, through the front contact and right-hand armature of relay 528, and thence over the circuit previously traced to the segment 127, and as soon as the shaft wiper 126 moves up off of 115 the first insulating portion of the segment, to ground through the wiper 126 over the circuit previously traced. Relay 524, upon energizing over this circuit, closes a locking 120 circuit for itself extending through its armature and front contact, through the winding of relay 523, and thence to ground through the lower left-hand and upper right-hand contacts of sequence switch spring 503. Relay 523, however, does not 125 energize over this circuit since its winding is shunted at the wiper 126 so long as the wiper 126 engages the conducting portion of the segment 127. As soon however, as the wiper 126 has moved upwardly into con- 130

tact with the second insulating portion of the segment 127, this shunt is removed and the relay 523 energizes. Upon energizing, it opens the initial energizing circuit of relay 524 at its left-hand armature and back contact and at its left-hand armature and front contact closes a circuit for relay 522 which is effective as soon as the wiper 126 again engages a conducting portion of the segment 127. This circuit may be traced from grounded battery, through the winding of relay 522, through the upper left-hand contact of sequence switch spring 505, through brush 545 of switch SLF, over bank contact N, thence to the junction point 5, through the front contact and left-hand armature of relay 523, through the contacts of sequence switch spring 517, through the front contact and right-hand armature of relay 528 and thence over the circuit previously traced, through the segment 127 and shaft wiper 126 to ground at the right-hand armature and front contact of relay 124. Relay 522, as previously described, now opens the circuit of relay 124 which in turn opens the circuit of the up-drive magnet 125. Relay 522 also closes at its right-hand armature and front contact, a circuit for driving sequence switch 500 out of position 7 and into position 8, this circuit extending through the magnet winding of the sequence switch, through the lower right-hand contact of sequence switch spring 508 (7), through the right-hand armature and front contact of relay 522, and thence to ground at the upper contact of sequence switch spring 503. The switch shaft of the line finder LF has now been driven upwardly through five steps and has positioned the fifth set of brushes in such a position relative to the tripping finger 6 of the tripping spindle 5 that, upon energization of the tripping magnet 128, this set of brushes is conditioned to be tripped in readiness to be traversed over its corresponding bank of contacts, upon a subsequent upward movement of the switch shaft. Relay 124, upon deenergizing, in addition to opening the circuit of the up-drive magnet 125, closes at its right-hand armature and back contact a circuit through the upper right-hand contact of sequence switch spring 108 for driving sequence switch 100 out of position 2 and into position 3, in which position a circuit is closed through the tripping magnet 128 and thence to ground through the upper right-hand contact of sequence switch spring 109.

It is to be noted that five junction terminals numbered 1 to 5 inclusive, are associated with the relays 523, 524, 527 and 528 of the link circuit shown in Fig. 5 for connection with bank terminals N appearing in the secondary line finders SLF, these junctions being connected into the banks of the secondary line finders in such manner that the tripping of a particular brush set of the line finder LF is made dependent upon a connection through the primary and secondary line finders to a subgroup in 70 which the calling line is located and which subgroup of lines is one of the three subgroups of thirty lines each to which the particular brush set of the line finder LF has access.

In position 3 of sequence switch 100, a circuit is closed for again energizing relay 124, which circuit extends through the winding of the relay, and thence to ground at the lower left-hand contact of sequence switch spring 105 (3). Upon energizing, relay 124 establishes a circuit through its right-hand armature and front contact and through the upper left-hand contact of sequence switch spring 108 (3) for driving sequence switch 100 out of position 3 and into position 4. In position 4, the initial energizing circuit of relay 124 is broken but the relay is maintained energized over a locking circuit extending through the resistance 129, through the left-hand contacts of sequence switch spring 110 (3 and 4), through the left-hand armature and front contact of relay 124, through the left-hand contact of sequence switch spring 107 (3 and 4), through the brush 544 of switch FS, and thence to grounded battery through the lower left-hand contact of sequence switch spring 518. A circuit is now established for the up-drive magnet 125 which may be traced through the winding of the magnet, through the left-hand contacts of sequence switch spring 106 (4), and thence to ground at the front contact and right-hand armature of relay 124. Magnet 125, upon energizing, 105 presses the depending portion of the switch shaft 1 against the constantly rotating up-drive roller 3, thereby causing the switch shaft to be driven upwardly and to traverse the tripped set of brushes 2 over the bank 110 contacts of the subgroup of ninety lines in which the calling line is located. This upward movement of the switch shaft continues until the test brush 130 engages the test terminal 131 corresponding to the calling line which has initiated the movement of the line finder LF, when a shunt circuit will be established around the left-hand winding of relay 124 for causing the de-energization thereof. This shunt circuit 120 may be traced from grounded battery at the left-hand lower contact of sequence switch spring 518, over the circuit previously traced to the left-hand winding of relay 124, and thence through the front contact and left-hand armature of this relay, through the left-hand contacts of sequence switch spring 111 (3 and 4), over brush 130 and the test terminal 131, over brush 411 of the primary line finder switch PLF which 125 130

has established a connection with the terminals of the calling line, through the left-hand armature and front contact of relay 412, through the wiper 548 of the secondary 5 switch SLF, and through the contacts of sequence switch spring 518 to grounded battery. If the line finder LF before reaching the terminal 131 of the calling line A had encountered a test terminal of another calling 10 line of the same subgroup, the shunt circuit around the winding of relay 124 would not have been established. It is therefore apparent that it is impossible for a line finder to make connection with the terminals of any 15 calling line other than the calling line which is through the operation of the primary and secondary line finders, initiating the hunting movement of the line finder LF.

Upon the establishment of the shunt 20 around the winding of relay 124, this relay becomes deenergized and at its right-hand armature and front contact opens the circuit of the up-drive magnet 125 and at its right-hand armature and back contact, establishes 25 a circuit through the upper right-hand contact of sequence switch spring 108 for driving sequence switch 100 out of position 4 and into position 5. The relay 124 however, does not deenergize immediately upon 30 the shunting out of its winding unless the brushes are properly centered upon the proper set of bank terminals since the relay 124 is held energized momentarily over a circuit extending through its right-hand 35 winding, through the upper right-hand contact of sequence switch spring 105 (3 $\frac{3}{4}$ and 4), through the segment 132 of the commutator 7, through the brush 126, and thence to ground through the upper left-hand contact of sequence switch spring 106 (4) and 40 through the front contact and right-hand armature of relay 124. When the brushes are properly centered the wiper 126 engages an insulating portion of the segment 132 45 and this locking circuit becomes destroyed.

When sequence switch 100 reaches position 4 $\frac{3}{4}$ a circuit is closed from grounded battery, through the right hand contacts of sequence switch spring 111 and thence through 50 brush 154 and to ground through the winding of cut-off relay 9. This circuit holds relay 9 energized and marks the multiple terminals of the calling line as busy. In position 5 of sequence switch 100, a circuit 55 is established for driving sequence switch 500, Fig. 5, out of position 8 and into position 10. This circuit may be traced from grounded battery through the magnet winding of sequence switch 500, through the 60 lower left-hand contact of sequence switch spring 519 (8), through brush 543 of the finder selector FS, over the bank terminal upon which it is resting, through sequence switch contact 122 (5), and thence to ground 65 at the back contact and right-hand arma-

ture of relay 124. A new impulse circuit is now established from the line of the calling subscriber through to the selected registering mechanism, since sequence switch 100 is now in position 5 and sequence switch 500 is in 70 position 10. This circuit may be traced from grounded battery through the right-hand winding of relay 613, through the contact of sequence switch spring 603, over bank terminal 533 of the switch RS, and the 75 wiper resting thereon, over the upper contact of sequence switch spring 515 (9 and 10), through brush 546 of the switch FS, over the bank terminal upon which it is resting, through the lower contact of sequence switch spring 112, through the wiper 133 of the line finder FL, over the subscriber's line loop and the impulse sender S thereat, and thence back through the wiper 134 of the finder LF, through the lower contact of sequence switch spring 113, through the wiper 547 of the switch FS, through the upper contact of sequence switch spring 516 (9 and 10), over brush 536 of switch RS, through the contact of sequence switch 90 604, and thence to ground through the left-hand winding of relay 613.

The calling subscriber, if he has not already finished dialing over the impulse circuit as established through the primary and 95 secondary line finder switches, may continue to send impulses over the circuit just traced through the wipers of the line finder LF.

When sequence switch 500 moves out of 100 position 9, the locking circuit for relay 412 and the energizing circuit of relay 405 become opened at sequence switch spring 502 and these relays thereupon deenergize. The deenergization of relay 405 restores the 105 circuits of the line finder PLF to normal condition in readiness for serving further calls in the subgroup of lines. Busy potential is removed at sequence switch spring 502 from the multiple contacts of the primary line finder which appear in the banks 110 of all secondary line finders.

Operation of selector switches.

Upon moving into position 5, sequence switch 100 prepares a fundamental circuit 115 for relay 135 which may be traced from grounded battery, through the left-hand winding of this relay, through the left-hand contacts of sequence switch spring 114, through the brush 544 of finder selector FS, 120 through the right-hand contacts of sequence switch spring 510, through brush 549, through sequence switch spring 610 (2 to 12), through the armature and back contact of relay 710, through the stepping relay 125 711 of the sender (Fig. 7) and thence to the lower left-hand contact of sequence switch spring 702. If, at this time, the subscriber has dialed the first two digits of 130 the desired number, sequence switch 600 will

have moved into position 6, in which position a circuit was established for driving sequence switch 700 out of position 1 and into position 2, this circuit being traced from 5 grounded battery, through the magnet winding of sequence switch 700, through the upper right-hand contact of sequence switch spring 703, and thence to ground through the upper right-hand contact of sequence 10 switch 602, and the circuit prepared for stepping relay 711 above traced becomes completed through the lower contacts of sequence switch spring 702. Relay 135, upon energizing, closes a locking circuit for its 15 self extending through its winding, through its left-hand armature and front contact to the sequence switch spring 114, and thence to ground at the lower right-hand contact of sequence switch spring 702, over the circuit 20 previously traced. At its right-hand armature and front contact, relay 135 closes a circuit extending over the lower right-hand contact of sequence switch spring 115 for driving sequence switch 100 out of position 5 and into position 6.

In position 6, a circuit is established for the up-drive magnet 136 of the district switch DS, this circuit extending from grounded battery, through the magnet 136, 30 through the lower contact of sequence switch spring 116 (6), and thence to ground at the front contact of relay 135. Upon energizing, magnet 136 presses the depending portion of switch shaft 1 against the constantly 35 rotating up-drive roller 3, thereby causing the switch shaft and the wipers carried thereby to be moved upwardly. Upon the engagement of the shaft wiper 137 with the first conducting portion of the commutator segment 138, a 40 branch circuit is connected from ground to the fundamental circuit at a junction point between the winding of relay 135 and the winding of the stepping relay 711. This branch circuit may be traced from ground, 45 through the upper right-hand contact of sequence switch spring 102, (11 to 9) through the wiper 137 and the segment 138, and thence to the junction point in the fundamental circuit, through the upper left-hand contact of sequence switch spring 117 (5 $\frac{3}{4}$ and 6). As soon as this branch circuit is closed, stepping relay 711 becomes shunted and retracts its armature, the relay 135 however, being maintained energized 50 over the branch circuit previously traced. Upon the initial energization of stepping relay 711, a circuit was closed from grounded battery, through the No. 2' counting relay, through the back contact and armature of 55 No. 2 counting relay, thence over the lead No. 2 to the corresponding lead in the middle bank of the district register, through the wiper 619 which has been set on the fifth contact of the register bank, through the 60 lower right-hand contact of sequence switch

spring 704, through the lower left-hand contact of sequence switch spring 705, through the front contact and armature of relay 711, and thence to ground through the lower right-hand contact of sequence switch spring 706. Relay 2' is energized in this circuit and locked up over a circuit extending through its winding, through the winding of the No. 2 counting relay, through the front contact and armature of No. 2' relay, and thence to ground at the lower contact of sequence switch spring 707. No. 2 counting relay does not energize however, in this circuit since its winding is shunted by the ground connection at the lower right-hand contact of sequence switch spring 706 which is connected thereto during the energization of the stepping relay 711. Upon the first deenergization of the stepping relay 711 as previously mentioned, when the shaft wiper 137 contacted with the first conducting portion of the commutator 138, this shunt circuit around the No. 2 counting relay was removed and the relay energized. Continued upward movement of the switch shaft 90 of the district switch DS again reestablishes a circuit through the stepping relay 711 which now causes the energization of the No. 1' counting relay over a circuit from grounded battery, through the winding of 95 this counting relay, through the back contact and armature of No. 1 counting relay, through the front contact and armature of the No. 2 counting relay and thence to ground at the lower right-hand contact of 100 sequence switch spring 706, over the circuit previously traced. The counting relays are thus successively energized in response to the movement of the shaft wiper 137 over the commutator segment 138 of the district selector DS until the last counting relay No. 0 energizes in parallel with relay 710. When this relay energizes a circuit is established for driving sequence switch 700 out of position 2 and into position 4, this circuit being traced from grounded battery, through the magnet winding of the sequence switch, through the armature and front contact of the No. 0 counting relay, and thence to ground at the upper contact of sequence 115 switch spring 707. The energization of relay 710 opens the fundamental circuit through stepping relay 711 and through the relay 135 of the district selector. The switch shaft of the district selector has now 120 been moved upwardly three steps, thereby positioning the third set of brushes having access to the twenty thousand line division of the exchange containing lines 40,000 to 59,999, inclusive in a position to be tripped 125 by the operation of the tripping spindle 5 during a subsequent upward movement of the switch shaft. Upon the deenergization of relay 135, sequence switch 100 is driven into position 7 by a circuit extending 130

through the magnet winding of the sequence switch, through the upper right-hand contact of sequence switch spring 115, and to ground through the right-hand armature 5 and back contact of relay 135. The circuit of the tripping magnet 139 is closed at the upper contacts of sequence switch spring 118, and spindle 5 is rotated into its tripping position.

10 In position 7, the fundamental circuit through the relay 135 of the district selector and the stepping relay 711 of the sender is again established from grounded battery, through the winding of relay 135, through 15 the left-hand contacts of sequence switch spring 114 (7), and thence over the fundamental circuit previously traced to ground at the lower contacts of sequence switch spring 702. The energization of relay 135 20 closes a circuit at its left-hand armature and front contact and thence over the fundamental circuit through the upper left-hand contact of sequence switch spring 114 for locking up the relay 135, and at its right-hand armature and front contact closes a 25 circuit extending through the lower contact of sequence switch spring 115 (7), for driving sequence switch 100 out of position 7 and into position 8. The circuit for the 30 up-drive magnet 136 is again established through sequence switch spring 116 (8) and thence to ground at the right-hand armature and front contact of relay 135, and the switch shaft is again driven upwardly. During 35 the initial upward movement the third set of brushes is tripped. The reestablishment of the fundamental circuit has again energized relay 711 which, since sequence switch 700 is now in position 4, closes a circuit 40 extending through the lower bank of the district register and through the No. 0' counting relay, which may be traced from grounded battery, through the winding of the No. 0' counting relay, over the conductor 45 No. 0 to the fifth terminal of the lowermost bank of the district register, through the wiper 620, through the lower left-hand contact of sequence switch spring 704 (4), through the lower right-hand contact of 50 sequence switch spring 705 (4), through the armature and front contact of stepping relay 711, and thence to ground through the upper right-hand contact of sequence switch spring 706 (4). Upon energization, the No. 55 0' counting relay locks up over a circuit extending through its winding, through the winding of the No. 0 counting relay, through the armature and front contact of the No. 0' counting relay, and thence to ground at the 60 lower contact of sequence switch spring 707. The No. 0 counting relay however, does not energize at this time as its winding is shunted by a ground connection at the upper right-hand contact of sequence switch spring 706. As soon as the selected set of brushes 65

of the district selector has been moved upwardly one step, in the case assumed to the bottom of the lower half of the bank having access to the 40,000 division of the exchange, the shaft wiper 140 will engage a conducting 70 portion of the commutator segment 141 and a shunt circuit will be closed from the junction point in the fundamental circuit between the winding of relay 135 and the winding of the stepping relay 711, which will 75 cause the deenergization of the stepping relay 711. This shunting circuit may be traced from the junction point at sequence switch spring 114, through the upper right-hand contact of sequence switch spring 117 (74 80 and 8), through the commutator segment 141, through brush 140 and thence to ground at the upper right-hand contact of sequence switch spring 102. The deenergization of relay 711 removes the shunt from around the 85 No. 0 counting relay and this relay energizes in parallel with the relay 710, and upon energizing closes a circuit through sequence switch spring 707 (4) for driving sequence switch 700 out of position 4 and into position 5. If at this time the calling subscriber has not completed the dialing of all of the digits of the desired line, sequence switch 600 will not have reached position 12 and, consequently the sequence switch 700 95 will remain in position 5 and thereby momentarily prevent the further functioning of the impulse sender. As soon however, as the number of the desired line has been completely dialed, sequence switch 600 is moved 100 into position 12 and a circuit is established for driving the sequence switch 700 into position 6, in which position the fundamental circuit is again established. The circuit for sequence switch 700 may be traced from 105 grounded battery, through the magnet winding of the sequence switch, through the upper left-hand contact of sequence switch spring 703, and thence to ground at the right-hand contact of sequence switch spring 611. Relay 710, upon energizing, opens the fundamental circuit through the stepping relay 711, and through the relay 135 of the district selector. The deenergization of relay 135 opens the circuit of the up-drive magnet 110 to arrest the upward movement of the switch shaft and at its right-hand armature and back contact, closes a circuit for driving sequence switch 100 out of position 8 and into position 9. 115

In position 9, relay 135 is again energized over a circuit extending from ground at the lower right-hand contact of sequence switch spring 119, through the right-hand winding of relay 135, and locks up through its left-hand winding and left-hand armature and front contact over a circuit extending through the upper right-hand contact of sequence switch spring 114 (9 to 17) to the test brush 142, and thence to ground on busy 120 125 130

test contacts of the terminal bank with which the test brush 142 contacts in the further upward movement of the switch brushes. At its right-hand armature and front contact, 5 a circuit is established over the lower contact of sequence switch spring 115 (9) for driving sequence switch 100 out of position 9 and into position 10, in which position, the circuit of the up-drive magnet 136 is again 10 established through the lower contact of sequence switch spring 116 (10) and the front contact and right-hand armature of relay 135. The energization of the up-drive magnet 136 causes the selected set of brushes to 15 be traversed over the bank terminals of the lower half of the bank with which they are adapted to coöperate until the test brush 142 engages the terminal contacts of a trunk circuit which is at the time idle, when no 20 ground potential will be found upon the test contact of the bank and the locking circuit of relay 135 will no longer exist. As the sequence switch 100 is now in position 10 and upon leaving position 9 opened the 25 initial energizing circuit of relay 135 at sequence switch spring 119, relay 135 de-energizes, opening at its right-hand armature and front contact, the circuit of the up-drive magnet 136 and closing at its right- 30 hand armature and back contact, a circuit for driving sequence switch 100 into position 11. The relay 135 does not however, de-energize immediately upon the opening of its locking circuit through test brush 142 35 unless the set of brushes are properly centered upon the selected set of bank contacts, since the relay 135 is momentarily held en- ergized over a circuit extending through its right-hand winding, through the upper con- 40 tact of sequence switch spring 119 (9 $\frac{1}{2}$ and 10), through the centering commutator seg- ment 143, through the shaft wiper 144, and thence to ground through the upper right- 45 hand contact of sequence switch spring 116 and the right-hand armature and front contact of relay 135. When, however, the brushes are properly centered, the shaft wiper 144 engages an insulating portion of the segment 143 and the circuit for relay 50 135 is opened.

Upon moving into position 11, the fundamental circuit extending from the sender relay 711 to the relay 135 of the district selector, is disconnected from relay 135 and 55 extended over brushes 145 and 146 of the district selector to the selected trunk circuit terminating in the incoming selector IS, Fig. 2. This circuit may be traced from grounded battery, through the right-hand 60 winding of relay 214, through the lower left-hand contact of sequence switch spring 202 (1), through the upper right-hand contact of sequence switch spring 203, through resistance 215, over the upper heavy con- 65 ductor of the trunk circuit, through brush 145 of the district selector, through the lower contacts of sequence switch spring 120 (11), through brush 544 of switch FS, through the right-hand contacts of sequence switch spring 510, through brush 549 of the register selector RS, through sequence switch spring 610, through the armature and back contact of relay 710, through the winding of relay 711, through the upper contacts of sequence switch spring 702, through the armature and front contact of relay 712, which is energized in position 6 of sequence switch spring 709, thence through the lower right-hand and upper left-hand contacts of sequence switch spring 605 (2 to 12), 70 through brush 550 of the register selector RS, through the lower right-hand contact of sequence switch spring 519 (10), through the brush 543 of the finder selector FS, through the lower contact of sequence switch spring 121 (11), over brush 146 of the district selector, and thence over the lower heavy conductor of the selected trunk circuit to ground at the lower contact of sequence switch spring 204 (1 to 13). Relays 75 214 and 711 energize in this circuit, relay 214 closing a locking circuit for itself extending through its right-hand armature and front contact, through the lower right-hand contact of sequence switch spring 202 (1 to 13), and thence over the fundamental circuit just traced. At its left-hand armature and front contact, relay 214 closes a circuit for relay 216 which may be traced from grounded battery, through the winding of the relay, through the lower contacts of sequence switch spring 205 (1) and thence to ground at the front contact and armature of relay 214. Relay 216 locks over 80 100 its right-hand armature and front contact, over a circuit extending through the test brush 142 of the district selector, through the upper right-hand contact of sequence switch spring 114, and thence to ground at the lower left-hand contact of sequence switch spring 117. At its left-hand armature and front contact, relay 216 closes a circuit for driving the sequence switch 200 out of position 1 and into position 2, which 105 circuit may be traced through the magnet 110 winding of the sequence switch, through the lower right-hand contact of sequence switch spring 206, thence to ground at the front contact and left-hand armature of relay 216. Upon leaving position 1, the initial 115 energizing circuit of relay 214 is opened at sequence switch spring 202. In position 2, sequence switch 200 closes a circuit for the up-drive magnet 217 of the incoming selector IS, which circuit extends from 120 grounded battery, through the winding of this magnet, through the lower contact of sequence switch spring 207 (2), and thence to ground at the front contact and right-hand armature of relay 214.

Magnet 217 is energized in this circuit and presses the depending portion of the switch shaft of the incoming selector against the constantly rotating up-drive roller 3, thereby causing the switch shaft and the brush sets carried thereby to be moved upwardly. Upon the energization of the stepping relay 711 of the sender, since the subscriber has positioned the brushes of the incoming selector register on the sixth set of bank contacts, a circuit is closed for the No. 2' counting relay which may be traced from grounded battery, through the winding of the No. 2' counting relay, through the armature and back contact of the No. 2 counting relay, over the No. 2 conductor to the sixth contact in the intermediate bank of the incoming selector register, through the wiper 623, through the upper right-hand contact of sequence switch spring 704 (6), through the left-hand contact of sequence switch spring 705, through the front contact and armature of the stepping relay 711 and thence to ground at the lower right-hand contact of sequence switch spring 706. Counting relay No. 2' energizes in this circuit and closes a locking circuit for itself extending through its winding, through the winding of the No. 2 counting relay, through the front contact and armature of the No. 2' counting relay, and thence to ground at the lower contact of sequence switch spring 707. The No. 2 counting relay does not energize in this circuit however, since its winding is at this time shunted by a ground connection at the lower right-hand contact of sequence switch spring 706. As soon however, as the switch shaft of the incoming selector has moved upwardly to a position in which the shaft wiper 218 engages the first conducting portion of the commutator segment 219, a shunt circuit is connected from ground to a junction point in the fundamental circuit between the relay 214 of the incoming selector and the stepping relay 711 of the sender, thereby causing the deenergization of the stepping relay 711 while maintaining the energization of the relay 214. This shunt circuit may be traced from the junction point at sequence switch spring 202, through the upper right-hand contact of this sequence switch spring, through the segment 219, through the shaft wiper 218, and thence to ground at the upper right-hand and lower left-hand contacts of sequence switch spring 208. Upon shunting out the stepping relay 711 and its consequent deenergization, the shunt circuit existing around the winding of the No. 2 counting relay is opened and this relay energizes, thereby extending the No. 2 conductor through its armature and front contact, through the armature and back contact of the No. 1 counting relay, through the winding of the No. 1' counting relay. As soon as the shaft wiper 218 has moved upwardly

out of contact with the first conducting portion of the segment 219 and into contact with the first insulating portion of this segment, the shunt circuit around the stepping relay 711 is opened and this relay again energizes, thereby causing the energization of the No. 1' counting relay. The counting relays thus operate in succession until the switch shaft has moved its brushes upwardly three steps, when the No. 0 counting relay will become energized in parallel with the relay 710 and will in the manner heretofore described, cause the movement of sequence switch 700 out of position 6 and into position 8.

The energization of relay 710 opens the fundamental circuit at its armature and back contact, thereby causing the deenergization of relay 214 of the incoming selector which, at its left-hand armature and front contact, opens the circuit of the up-drive magnet 217 and, at its left-hand armature and back contact, closes a circuit for driving the sequence switch 200 out of position 2 and into position 3, this circuit extending from grounded battery, through the winding of the sequence switch magnet 200, through the upper right-hand contact of sequence switch spring 209, and thence to ground at the armature and back contact of relay 214. The switch shaft of the incoming selector has now moved its brush sets 2 upwardly into such a position that the third set of brushes is in a position to be tripped by the operation of the tripping spindle 5 through the energization of tripping magnet 220 upon a subsequent upward movement of the switch shaft. The circuit of tripping magnet 220 extends from grounded battery, through the winding of this magnet, through the lower right-hand contact of sequence switch spring 210 (3 and 4), and thence to ground at the lower left-hand contact of sequence switch spring 208.

With the sequence switch 200 in position 3 and sequence switch 700 in position 8, the fundamental circuit previously traced through relay 214 of the incoming selector and the stepping relay 711 of the sender is again established and these relays both become energized. Upon the energization of relay 214, a circuit is established at its left-hand armature and front contact extending through the lower right-hand contact of sequence switch spring 209 for driving sequence switch 200 out of position 3 and into position 4. Upon leaving position 3, the initial energizing circuit of relay 214 is broken at the lower left-hand contact of sequence switch spring 202, but the relay 214 is locked up over the fundamental circuit by reason of a new circuit extending from sequence switch spring 203, through the lower right-hand contact of sequence switch spring 202, through the right-hand armature and front contact of relay 214, and thence

through the winding of relay 214 to grounded battery.

In position 4 of sequence switch 200, relay 214 at its left-hand armature and front contact, again establishes the circuit of the up-drive magnet 217, which thereupon energizes and again causes the upward movement of the switch shaft. During the initial portion of the upward movement the third set of brushes is tripped and this set of brushes is the only set which is traversed over the contacts of its corresponding bank of contacts. The energization of stepping relay 711, since the subscriber has positioned the wipers of the incoming selector register upon the sixth set of bank contacts and has positioned the wipers of the hundreds register upon the seventh set of bank contacts, closes the circuit for the No. 3' counting relay which may be traced from grounded battery, through this relay, through the back contact and armature of the No. 3 counting relay, over the No. 3 conductor to the seventh bank contact of the hundreds register, through the wiper 628, through the sixth bank contact of the lowermost bank of the incoming selector register, through the wiper 624, through the lower left-hand contact of sequence switch spring 708 (8), through the lower right-hand contact of sequence switch spring 705, through the armature and front contact of relay 711, thence to ground through the upper right-hand contact of sequence switch spring 706. The No. 3' counting relay energizes in this circuit and locks up in the well-known manner through the winding of the No. 3 counting relay. The No. 3 counting relay however, does not energize at this time, since its winding is shunted by ground at sequence switch spring 706. As soon however, as the selected brush set of the incoming selector has been moved upwardly one step, the shaft wiper 221 engages the first conducting portion of the commutator segment 222, thereby closing a shunt circuit around the winding of the stepping relay 711 for causing its deenergization while maintaining the energization of the relay 214. This shunt circuit may be traced from a junction point at sequence switch spring 203 between the winding of the stepping relay 711 and the winding of relay 214, through the left-hand contacts of this sequence switch spring, through the commutator segment 222, through the shaft wiper 221, and thence to ground at the upper right-hand and lower left-hand contacts of sequence switch spring 208. Relay 711, upon deenergizing, removes the shunt from around the No. 3 counting relay which thereupon energizes and, at its armature and front contact, extends the No. 3 conductor through the armature and back contact of the No. 2 counting relay to the winding of the No. 2' counting relay. As soon as the

switch shaft of the incoming selector moves upwardly off of the first conducting portion of the segment 222 and into contact with the first insulating portion of this segment, the fundamental circuit is again established 70 through the stepping relay 711 which now causes the energization of the No. 2' counting relay, the counting relays thus operate in succession until the switch shaft of the incoming selector has taken four full steps 75 when the No. 0 counting relay becomes energized in parallel with relay 710 and, at its armature and front contact, closes the circuit previously traced for driving the sequence switch 700 out of position 8 and 80 into position 10. Relay 710, upon energizing again opens the fundamental circuit, thereby causing the deenergization of relay 214, which, upon deenergizing, opens the circuit at its left-hand armature and front contact 85 through the winding of the up-drive magnet to thereby stop the upward movement of the switch shaft, and at its left-hand armature and back contact, closes a circuit extending through the upper right-hand contact of sequence switch spring 209 for driving the sequence switch out of position 4 and into position 5.

Upon moving into position 5, sequence switch 200 closes a circuit through the left-hand winding of relay 214 which extends from grounded battery, through the left-hand winding of the relay and thence to ground at the lower contact of sequence switch spring 211. Relay 214 is energized 95 in this circuit and, at its left-hand armature and front contact, closes a circuit for driving the sequence switch 200 out of position 5 and into position 6. When the sequence switch leaves position 5, the initial energizing circuit of the relay 214 is broken at sequence switch spring 211 but the relay will remain energized over a locking circuit extending from grounded battery, through its right-hand winding, right-hand armature and front contact, through the lower left-hand contact of sequence switch spring 202, through the lower right-hand contact of sequence switch spring 203 (5 to 7), and thence to the test brush 223, and to ground 100 105 110 115 encountered by this test brush on all test contacts of its bank corresponding to busy trunks leading to final connectors of the group selected by the incoming selector.

In position 6 of the sequence switch 200, 120 the circuit of the up-drive magnet 217 is again closed over a circuit extending through the winding of the magnet, through the lower contact of sequence switch spring 207, and thence to ground at the front contact and left-hand armature of relay 214. The energization of the up-drive magnet causes the selected set of brushes to be traversed upwardly over the selected portion 125 of its bank which, in the case assumed, is 130

the fourth or uppermost subgroup of contacts in this bank. This upward movement of the brushes will continue so long as the test brush 223 encounters busy ground potential upon the test contacts of the bank. 5 As soon however, as the contacts of an idle trunk are encountered, the locking circuit of relay 214 is no longer maintained over the test wiper 223. The relay 214 is, 10 however, maintained energized until the brushes are properly centered on the contacts of the idle trunk by a circuit extending through the left-hand winding of relay 214, through the upper contact of sequence switch spring 211 (6), through the commutator segment 224, through the shaft wiper 225 and thence to ground through the upper contact of sequence switch spring 207 and the left hand armature and the front contact of relay 214. 15 As soon as the brushes are properly centered on the bank contacts, relay 214 deenergizes, opening at its left-hand armature and front contact, the circuit of the up-drive magnet 217 and closing at its left-hand armature and back contact, a circuit for driving the sequence switch 200 out of position 6 and into position 8. Upon leaving position 6 and moving into position 25 20, a circuit is closed from ground, through the left-hand contacts of sequence switch spring 208 for placing busy ground potential on multiple terminals of the selected trunk, through the test brush 223 for preventing other incoming selector switches from seizing the selected trunk circuit.

With sequence switch 200 in position 8 and sequence switch 700 in position 10, the fundamental circuit previously traced through the relay 214 of the incoming selector and the stepping relay 711 of the sender 40 is again reestablished and these relays become energized. The energization of relay 214 closes a circuit extending through its left-hand armature and front contact for driving sequence switch 200 out of position 8 and into position 9, and at its right-hand armature and front contact, closes a locking circuit for itself extending back over the fundamental circuit for replacing the 45 initial energizing circuit which opens as soon as sequence switch 200 leaves position 8. In position 9 of sequence switch 200, a circuit is now established for relay 313 of the final selector which may be traced from the grounded battery, through the winding of 50 this relay, through the upper right-hand contact of sequence switch spring 302, over the upper heavy conductor (Fig. 3), through the brush 226 of the incoming selector, 55 through the lower left-hand contact of sequence switch spring 212 (9), and thence to ground at the front contact and left-hand armature of relay 214. Relay 313 energizes in this circuit and at its left-hand armature 60 in this circuit and at its left-hand armature 65 and front contact, closes a circuit for the

relay 314, which circuit may be traced from grounded battery, through the winding of this relay, through the lower contacts of sequence switch spring 303, and thence to ground through the front contact and left-hand armature of relay 313. Relay 314 upon energizing, closes a locking circuit for itself extending over its left-hand armature and front contact, through the test brush 223 of the incoming selector, and thence to ground at the left-hand contacts of sequence switch spring 208, and at its right-hand armature and front contact, closes a circuit extending from ground, through the upper left-hand contact of sequence switch spring 304 for driving sequence switch 300 out of position 1 and into position 2. Upon leaving position 1, the initial energizing circuit of relay 313 was opened at the right-hand contact of sequence switch spring 302 but the relay 313 is maintained energized over a locking circuit which extends through its winding, through the left-hand contact of sequence switch spring 305 (1 to 6), through the front contact and right-hand armature 70 of relay 313, through the left-hand contact of sequence switch 302, and thence over the circuit previously traced to ground at the left-hand armature and front contact of relay 214. Relay 313 now closes a circuit 75 for the high speed up-drive magnet 315 which may be traced from grounded battery, through this magnet, through the upper right-hand contact of sequence switch spring 305 (2), through the front contact 80 and right-hand armature of relay 313, and thence over the circuit previously traced to ground at the front contact and left-hand armature of relay 214. The up-drive magnet 314 is energized in this circuit and 85 presses the depending portion of the switch shaft of the final selector against the constantly rotating up-drive roller 10, whereby the switch shaft with its associated sets of wipers 2 is driven upwardly. 90

The stepping relay 711 of the sender is, as above noted, energized in the fundamental circuit, and since the calling subscriber has positioned the wipers of the hundreds register on the seventh set of bank contacts, 95 closes a circuit for the No. 1' counting relay which may be traced from grounded battery, through the No. 1' counting relay, through the back contact and armature of the No. 1 counting relay, over the No. 1 conductor, to the seventh contact of the lowermost bank of the hundreds register, through the wiper 629 in engagement therewith, 100 through the upper left-hand contact of sequence switch spring 708 (10), through the lower left-hand contact of sequence switch spring 705, through the contact and armature of the stepping relay 711, and thence to ground through the lower right-hand contact of sequence switch spring 706. The 105

115

120

125

130

counting relay 1' energizes in this circuit and locks up through the winding of the No. 1 counting relay previously described, but the No. 1 counting relay does not energize at this time since its winding is shunted by the ground connection at the sequence switch spring 706. As soon however, as the shaft of the final selector switch has moved one complete step, the shaft wiper 337 will engage the first conducting portion of the commutator segment 338 and a circuit will be established for shunting the stepping relay 711 which will thereupon de-energize, removing the shunt from around the No. 1 counting relay. The shunt circuit established at the final selector switch may be traced from ground at the upper left-hand contact of sequence switch spring 306, through the shaft wiper 337, through the commutator segment 338, through the upper right-hand contact of sequence switch spring 307 (1 $\frac{1}{4}$ and 2), through the upper left-hand contact of sequence switch spring 308 (1 to 7), over the lower heavy trunk conductor in Fig. 3, over the brush 227 of the incoming selector switch, through the lower left-hand contact of sequence switch spring 213, and thence to a junction point between the winding of relay 214 and the winding of the stepping relay 711 of the sender. Upon the de-energization of the stepping relay 711 and the consequent energization of the No. 1 counting relay, the No. 1 lead becomes connected through the armature and front contact of the No. 1 counting relay to the winding of the No. 0' counting relay and upon the next energization of the stepping relay 711 when the shaft wiper 337 has moved upwardly out of contact with the first conducting portion of the segment 338 and into contact with the first insulating portion, thereof the stepping relay 711 becomes energized over the fundamental circuit, thereby causing the energization of the No. 0' counting relay which in the well-known manner locks up and prepares a circuit for the 0 counting relay. After the completion of the second full step of the switch shaft of the final selector, the stepping relay 711 is again de-energized and the 0 counting relay energizes in parallel with the relay 710, the 0 counting relay closing a circuit at its armature and front contact for driving sequence switch 700 out of position 10 and into position 12, and the relay 710 opening the fundamental circuit and thereby causing the de-energization of the relay 214.

The de-energization of relay 214 opens at its left-hand armature and front contact the circuit of the up-drive magnet 315 of the final selector, thereby causing the switch shaft to be brought to rest. With its brush sets so positioned with relation to the tripping spindle 5 that upon the subsequent energization of the tripping magnet 316 and

upward movement of the switch shaft, the second set of brushes will become tripped, this set of brushes having access to the hundred lines including lines 45,600 to 45,699. At its left-hand armature and back contact, relay 214 establishes a circuit through the upper right-hand contact of sequence switch spring 209 for driving sequence switch 200 out of position 9 and into position 10. Relay 214 also opens the circuit of relay 313 which thereupon de-energizes, closing at its left-hand armature and back contact, a circuit extending over the lower right-hand contact of sequence switch spring 304 for driving sequence switch 300 out of position 2 and into position 3.

With sequence switch 200 in position 10 and sequence switch 700 in position 12, the fundamental circuit extending through relays 214 and 711 is re-established and these relays become energized. Relay 214, upon energization, closes a circuit at its left-hand armature and front contact for driving sequence switch 200 out of position 10 and into position 11, and at its right-hand armature and front contact, closes a locking circuit for itself through the lower right-hand contact of sequence switch spring 202, and thence over the fundamental circuit, for replacing its initial energizing circuit which becomes broken at the lower left-hand contact of sequence switch spring 202 as soon as the sequence switch moves out of position 10. At its left-hand armature and front contact, relay 214 also closes a circuit which extends through the lower left-hand contact of sequence switch spring 212 (11), and thence over the circuit previously traced, through the winding of relay 313 at the final selector switch. Relay 313 energizes in this circuit and at its left-hand armature and front contact, closes a circuit through the lower left-hand contact of sequence switch spring 304 for driving sequence switch 300 out of position 3 and into position 4.

In position 4, the circuit of the high speed updrive magnet 315 is again established over the circuit previously traced, extending to ground at the left-hand armature and front contact of relay 214 and, by its energization, causes the switch shaft of the final selector to be driven upwardly. Upon the establishment of the fundamental circuit through the stepping relay 711, the relay 711 energizes and, since the subscriber has positioned the brushes of the tens register upon the ninth set of bank contacts, closes a circuit extending from grounded battery, through the No. 8' counting relay, through the back contact and armature of the No. 8 counting relay, over the No. 8 conductor to the ninth terminal of the lowermost bank of the tens register, thence over the brush 632 in engagement with this bank contact, through the upper right-hand contact or se-

quence switch spring 708 (12), through the lower right-hand contact of sequence switch spring 705, through the armature and front contact of relay 711, thence to ground 5 through the upper right-hand contact of sequence switch spring 706. Counting relay 8' energizes in this circuit and closes a locking circuit for itself through the winding of the No. 8 counting relay but since the No. 8 10 counting relay is at this time shunted by the ground connection at sequence switch spring 706, the No. 8 counting relay does not energize. As soon, however, as the switch shaft has moved upwardly until the shaft 15 wiper 335 contacts with the first conducting portion of the commutator segment 336, a shunt circuit is established for shunting the stepping relay 711 to thereby cause its de-energization. This shunt circuit may be 20 traced from the junction point at sequence switch spring 203 in the fundamental circuit, between the winding of stepping relay 711 and the winding of relay 214, over the lower left-hand contact of sequence switch 25 spring 213 (10 $\frac{1}{2}$ to 11), over the brush 227 of the incoming selector switch, through the upper left-hand and lower right-hand contacts of sequence switch spring 308, through the commutator segment 336 and the shaft 30 wiper 335 to ground at the upper left-hand contact of sequence switch spring 306. This shunt circuit maintains the relay 214 energized. Relay 711, upon de-energizing, removes the shunt from the winding of the 35 No. 8 counting relay which thereupon energizes, extending the No. 8 conductor through its armature and front contact, through the armature and back contact of the No. 7 counting relay to the winding of 40 the No. 7' counting relay. Continued upward movement of the switch shaft moves the shaft wiper 335 off of the conducting portion of commutator segment 336 on to the first insulating portion of this segment, 45 whereupon the shunt around the relay 711 is opened and the stepping relay again energizes causing the energization of the No. 7' counting relay. The counting relays operate in succession in the manner set forth until 50 the selected set of switch brushes in the final selector switch have been moved upwardly to the bottom of the ninth subgroup of bank contact containing the terminals of lines 45,680 to 45,689, in which the line of 55 desired subscriber terminates when counting relay No. 0 will become energized in parallel with the relay 710, closing at its armature and front contact, a circuit for driving sequence switch 700 out of position 12 and 60 into position 14. Relay 710, at its armature and back contact, opens the fundamental circuit causing the de-energization of relay 214.

Relay 214, upon de-energizing, opens at its 65 left-hand armature and front contact the

circuit of the up-drive magnet 315 of the final selector which thereupon de-energizes, causing the switch shaft to be brought to rest. Relay 214 also opens the circuit previously traced which, in position 4 of sequence 70 switch 300, extends through the winding of relay 313 and this relay de-energizes closing, at its left-hand armature and back contact, a circuit for driving sequence switch 300 out of position 4 and into position 5. At its 75 left-hand armature and back contact, relay 214 closes a circuit for driving sequence switch 200 out of position 11 and into position 12.

With sequence switch 200 in position 12 80 and sequence switch 700 on position 14, the fundamental circuit for relays 214 and 711 is again established and these relays become energized. Relay 214, at its left-hand armature and front contact closes a circuit for driving sequence switch 200 into position 13 and, at its right-hand armature and front contact, closes a locking circuit for itself extending through the lower right-hand contact of sequence switch spring 202 and 90 thence over the fundamental circuit, for replacing the initial energizing circuit of relay 214 which becomes opened at the lower left-hand contact of sequence switch spring 202 when the sequence switch 200 moves out 95 of position 12. In position 13, a circuit is closed extending from the left-hand armature and front contact of relay 214, through the lower left-hand contact of sequence switch spring 212 (13), thence over the 100 circuit previously traced, through the winding of relay 313. This relay thereupon energizes closing at its left-hand armature and front contact, a circuit for driving sequence switch 300 out of position 5 and into position 105 6, and closing at its right-hand armature and front contact, a locking circuit for itself extending through the upper left-hand contact of sequence switch spring 302 and thence over the circuit previously traced 110 to ground at the left-hand armature and front contact of relay 214.

A circuit is now established for the slow speed up-drive magnet 317 which may be traced from grounded battery, through the winding of this magnet, through the lower right-hand contact of sequence switch spring 305 (6), through the front contact and right-hand armature of relay 313, and thence over the circuit previously traced 115 to ground at the left-hand armature and front contact of relay 214. The magnet 317 energizes and presses the depending portion of the switch shaft 1 against the constantly rotating slow speed roller 3, thereby causing 120 further upward movement of the switch shaft. Relay 711 now closes a circuit for the No. 9' counting relay, which circuit extends from grounded battery, through this 125 counting relay, through the back contact 130

- and armature of the No. 9 counting relay, through the No. 9 conductor to the tenth bank contact in the lowermost bank of the units register, through the wiper 635, 5 through the lower right-hand contact of sequence switch spring 708 (14), through the lower left-hand contact of sequence switch spring 705, through the front contact and armature of relay 711, thence to ground 10 through the lower right-hand contact of sequence switch spring 706. This counting relay thereupon energizes and closes a locking circuit for itself extending through the winding of the No. 9 counting relay but the 15 No. 9 counting relay does not energize at this time since its winding is shunted by the ground connection at the sequence switch spring 706. As soon, however, as the switch shaft has moved upwardly until the 20 shaft wiper 337 contacts with the conducting portion of the segment 338, a shunt circuit is closed around the winding of the stepping relay 711 and this relay deenergizes, thereby removing the shunt from the 25 winding of the No. 9 stepping relay. The shunt circuit of the final selector switch may be traced through the sequence switch spring 203, through the lower left-hand contact of sequence switch spring 213 (12 $\frac{1}{2}$ to 30 13), through the brush 227 of the incoming selector, through the upper left-hand contact of sequence switch spring 308, through the upper right-hand contact of sequence switch spring 307 (5 $\frac{1}{2}$ and 6), through the 35 segment 338 and brush 337 the lower left-hand contact of sequence switch spring 306 and thence to ground at the left-hand armature and front contact of relay 313. As soon as the shunt is removed from around the 40 winding of the No. 9 counting relay, it energizes and at its armature and front contact extends the No. 9 conductor through the armature and back contact of the No. 8 counting relay to the winding of the No. 8' counting relay. Further upward movement of the shaft of the final selector removes the shunt existing through the shaft wiper 337 and the segment 338, whereupon the stepping relay 711 again energizes and establishes an energizing circuit for the No. 8' counting relay. The counting relays thereupon operate in succession until the shaft of the final selector switch has moved its brushes upwardly to the last terminal of 50 the subgroup which has been assumed to be the terminal of the desired line, when the No. 0 counting relay will become energized in parallel with relay 710, closing at its armature and front contact a circuit for 55 driving sequence switch 700 out of position 14 and into position 18. Relay 710, at its armature and back contact, opens the fundamental circuit extending through the relays 711 and 214. Relay 214 thereupon de- 60 energizes, closing at its left-hand armature and back contact, a circuit for driving sequence switch 200 out of position 13 and into position 14, and at its left-hand armature and front contact, opens the circuits previously traced for the up-drive magnet 70 317 and the relay 313. The up-drive magnet thereupon deenergizes and the switch shaft comes to rest with its wipers positioned upon the terminals of the desired line. Relay 313, upon deenergization, closes at its 75 left-hand armature and back contact, a circuit for driving sequence switch 300 out of position 6 and into position 7.
- Restoration of register mechanism.*
- When sequence switch 700 of the sender moved into position 18, a circuit was established for driving the sequence switch 600 out of the registering mechanism out of position 12 and into position 17. This circuit 80 extends from grounded battery, through the magnet winding of the sequence switch 600, through the lower right-hand contact of sequence switch spring 608 (12), and thence to ground at the upper left-hand contact of 85 sequence switch spring 706 (18). In position 17, sequence switch 600 now closes a restoring circuit for starting the restoration of the registering members of the registering mechanism to normal position. 90 This circuit extends from grounded battery, through the stepping magnet 633 of the units register member, through its interrupter contacts, through the uppermost bank contact of the units register, through the 95 wiper 634, and thence to ground at the lower right-hand contact of sequence switch 602 (17). Stepping magnet 633 thereupon steps its wipers on around to normal position, when the wiper 634 disengages its bank contacts and engages its normal contact 636. A circuit is now established for the stepping magnet 630 of the tens register which extends through the winding of the stepping magnet and its interrupter contacts, through 100 the uppermost bank contact of the tens register, through the wiper 631, through the normal contact 636, through the wiper 634 of the units register in normal position, and thence to ground at the lower right-hand 105 contact of sequence switch spring 602. In this manner the stepping magnets 625, 621, and 617 of the hundreds, incoming and district registers are energized to restore their 110 respective registers to normal position when a circuit becomes effective for driving sequence switch 600 out of position 17 and into position 18, this circuit extending from grounded battery, through the winding of the sequence switch magnet, through the 115 lower left-hand contact of sequence switch spring 608, through the normal position contacts of the several registers and corresponding to the normal position contact 636 of the units register and thence to ground at the 120 125 130

lower right-hand contact of sequence switch spring 602. In position 18, sequence switch 600 closes a circuit for driving sequence switch 700 out of position 18 and into normal position, this circuit extending from grounded battery, through the magnet winding of sequence switch 700, through the lower left-hand contact of sequence switch spring 703, and thence to ground at the lower left-hand contact of sequence switch spring 611 (18). Sequence switch 700 in position 1 closes a circuit for driving sequence switch 600 out of position 18 and into normal position 1, this circuit extending from grounded battery, through the magnet winding of sequence switch 600, through the lower right-hand contact of sequence switch spring 612 (18), and thence to ground through the upper left-hand contact of sequence switch spring 709. The impulse registering mechanism and the sending mechanism are now restored to normal position since relays 613 and 614 became deenergized as soon as sequence switch 600 left position 17, and therefore opened the locking circuit of relay 616.

Upon the movement of sequence switch 600 out of position 12, the circuit which has been maintaining relay 529 energized is opened at sequence switch spring 606. Relay 529 thereupon deenergizes closing, at its left-hand armature and back contact, a circuit extending through the magnet winding of sequence switch 500, through the lower left-hand contact of sequence switch contact 509 (5 to 10), through the back contact and left-hand armature of relay 529, and thence to ground at the lower right-hand contact of sequence switch spring 511. Sequence switch 500 now moves out of position 10 and into position 18. In position 18, a circuit is established for the down-drive magnet 551 of switch FS which may be traced from grounded battery, through the winding of this magnet, and thence to ground through the upper left-hand and lower right-hand contacts of sequence switch 511. The energization of the down-drive magnet 551 presses the depending portion of the switch shaft against the constantly rotating down-drive roller 4, thereby causing the switch shaft 1 to be moved downwardly into normal position. In its normal position, a circuit is closed for driving sequence switch 500 out of position 18 and into normal position 1, which circuit may be traced through the winding of the sequence switch magnet, through the upper right-hand contact of sequence switch spring 509, and thence to ground through the normal commutator segment 552 and through the shaft wiper 541. The circuits of the register selector link are now in normal condition.

Upon leaving position 12, after all impulses have been sent for setting the selector switches for establishing the connection be-

tween the calling and called lines, sequence switch 600 opens at sequence switch spring 606, the circuit which has maintained relay 123, Fig. 1, energized and this relay deenergizes, closing, at its right-hand armature and back contact, a circuit extending through the upper left-hand contact of sequence switch spring 104 (2 to 11) for driving sequence switch 100 out of position 11 and into position 12. Upon leaving position 11, the impulse circuit which extended through the sequence switch springs 112 and 113, through the brushes of switches FS and RS to the registering mechanism, is opened and the brushes 133 and 134 of the line finder LF are connected over the upper contacts of these sequence switch springs to the left-hand windings of repeating coil 149. The fundamental circuit is also disconnected at this time at the lower contacts of sequence switch springs 120 and 121, from the brushes 145 and 146 of the district selector switch and the brush 146 is connected over the upper contact of sequence switch spring 121 to the winding of the calling supervisory relay 152.

Upon the extension of the calling line to the repeating coil 149 shown in Fig. 1, a circuit is established through the winding of the answering supervisory relay 147, which relay energizes over the left-hand windings of the repeating coil 149 and over the subscriber's line loop. This relay, upon energizing, closes at its armature and front contact, a circuit for the slow relay 148 which, upon energizing, closes a circuit through the upper right-hand contact and the lower left-hand contact of sequence switch spring 103 for relay 123. Relay 123 energizes and at its right-hand armature and front contact closes a circuit extending through the upper right-hand contact of sequence switch spring 104 for driving sequence switch 100 out of position 12 and into position 13, and at its left-hand armature and front contact, closes a locking circuit for itself to replace the initial energizing circuit which is broken at the lower left-hand contact of sequence switch spring 103 when the sequence switch 100 moves out of position 12 into position 13. The sequence switch 100 remains in this position during conversation and until the calling subscriber initiates the release of the central station apparatus.

As soon as the brushes 145 and 146 of the district selector are connected through to the strands of the link circuit in Fig. 1, a circuit is established for the relay 214 which may be traced from grounded battery, through the right-hand winding of this relay, through the lower left-hand contact of sequence switch spring 202 (14), through the upper right-hand contact of sequence switch spring 203 (8 to 14), thence over the upper heavy talking conductor in Fig. 2,

through the brush 145 of the district selector switch, through the lower right-hand and upper left-hand contacts of sequence switch 120, and thence through the upper right-hand winding of repeating coil 149 to ground. Relay 214 energizes in this circuit and at its left-hand armature and front contact, closes a circuit for driving the sequence switch 200 out of position 14 and into ringing position 15. As soon as sequence switch 200 leaves position 14, the energizing circuit of relay 214 is opened and the relay is deenergized.

With sequence switch 200 in position 15 and sequence switch 300 in position 7, a circuit is established for relay 313 which may be traced from grounded battery, through the winding of this relay, through the upper right-hand contact of sequence switch spring 202, through the switch brush 226, and thence to ground at the lower right-hand contact of sequence switch spring 212. Relay 313 energizes in this circuit and at its left-hand armature and front contact, closes a circuit through the lower left-hand contact of sequence switch spring 304 for driving sequence switch 300 out of position 7 and, under the influence of its master contact 301, into position 13.

30 Extension of call to an idle direct line.

In position 8 the terminals of the called line are tested to determine the busy or idle condition of the line. Assuming that the line is idle, when the test brush 320 engages the test terminal of the line, a circuit is established through the right-hand winding of the cut-off relay 9' of the called line, the right-hand winding only of the cut-off relay being employed on direct lines and the last line of a P. B. X. group, through the test brush 320, through the lower left-hand contact of sequence switch spring 309, and through the winding of the test relay 321, and thence to grounded battery through the left-hand winding of the test relay 322. Relay 322 energizes in this circuit and locks up through its right-hand winding, right-hand armature contacts and the upper right-hand contact of sequence switch spring 309. Since relay 313 deenergizes as soon as sequence switch 300 left position 7, the sequence switch 300 continues to move through position 13 by virtue of an energizing circuit for the winding of the sequence switch magnet extending through the lower right-hand contact of sequence switch spring 304, and back contact and armature of relay 313, and by reason of a further driving circuit which becomes established when the sequence switch reaches position 15 which extends through the winding of the sequence switch magnet, through the lower right-hand contact of sequence switch spring 310, and thence to ground at the front contact and

left-hand armature of the energized test relay 322. Sequence switch 300 therefore comes to rest in position 16, in which position, the sequence switch springs 302 and 303 extend the talking conductors of the trunk circuit through from the bank terminals of the incoming selector switch to the brushes 323 and 324 of the final selector switch. In this position test relay 322 remains locked up over its right-hand winding and the left-hand contact of sequence switch spring 309.

Ringing over the called line.

A circuit is now established for ringing current which may be traced from a suitable source of ringing current (not shown), through the winding of the ringing cut-off relay 228, Fig. 2, through the upper right-hand contact of the sequence switch spring 213, over the brush 227, through the upper contacts of sequence switch spring 308, over brush 324, over the subscriber's line loop, through the ringer 325 at the substation B, thence back over the brush 323 of the final selector switch, through the lower right-hand contact of sequence switch spring 302, through the brush 226, of the incoming selector switch, and thence to ground at the lower right-hand contact of sequence switch spring 212. Ringing tone is transmitted to the calling line over the upper contact of spring 204 and through condenser 229.

Response of called subscribers.

Upon the response of the called subscriber the resistance of the line loop becomes reduced by the removal of the receiver from the switch-hook, and the ringing cut-off relay 228 thereupon becomes energized, closing at its armature and front contact, a circuit extending through the left-hand contact of sequence switch spring 209 for driving sequence switch 200 out of the ringing position 15 and into the talking position 16, in which position the talking strands of the trunk circuit are made continuous at the upper left-hand contacts of sequence switch springs 212 and 213. Conversation may now take place between the substation A of the calling line and the substation B of the called line, the calling subscriber receiving talking current through the left-hand windings of the repeating coil 149 in Fig. 1, and the called subscriber receiving talking current through the right-hand windings of this repeating coil.

Restoration of central station apparatus.

Upon the termination of the conversation, both subscribers return their receivers to their respective switchhooks. Upon the return of the calling subscriber's receiver to its switchhook, the circuit of the answering supervisory relay 147 is opened and this re-

100

105

110

115

120

125

130

lay opens the circuit of the relay 148 which, after an interval, opens the circuit of relay 123. This relay, upon deenergizing, closes a circuit for driving sequence switch 100 out of position 13 and into position 16. In position 16, the brushes of the line finder are disconnected at sequence switch contacts 112 and 113 from the strands of the link circuit, and a circuit is closed for the down-drive magnet 150 which extends from battery, through the winding of this magnet and thence to ground at the lower contact of sequence switch spring 109. Magnet 150, upon energizing, presses the depending portion of the switch shaft against the constantly rotating down-drive roller 4, thereby driving the shaft of the line finder LF into normal position. When the switch shaft reaches normal position, a circuit is closed for driving sequence switch 100 out of position 16 and into position 17, this circuit extending through the winding of the sequence switch magnet, through the lower left-hand contact of sequence switch spring 108, through the normal segment 151 of the commutator 7, through the brush 126 now in engagement therewith, and thence to ground at the lower right-hand contact of sequence switch 106.

Sequence switch 100 now remains in position 17 awaiting the restoration of the called subscriber's receiver to its switchhook. When the called subscriber hangs up his receiver, the calling supervisory relay 152 becomes deenergized and at its armature and back contact, closes a circuit through the lower left-hand contact of sequence switch spring 104 for driving sequence switch 100 out of position 17 and into position 18. In position 18, a circuit is established for the down-drive magnet 153 of the district selector switch which circuit may be traced from grounded battery, through the winding of magnet 153, and thence to ground through the lower contact of sequence switch spring 118. The magnet 153, upon energizing, presses the depending portion of the switch shaft against the constantly rotating down-drive roller 4, thereby causing the switch shaft to be restored to normal position, in which position a circuit is established for driving sequence switch 100 out of position 18 and into its normal position, this circuit extending through the winding of the sequence switch magnet, through the lower right-hand contact of sequence switch spring 108, through the normal segment 154 of the commutator 7, through the brush 144, and thence to ground at the upper right-hand contact of sequence switch spring 102. The line finder LF and the district selector DS are now in normal position and all circuits associated therewith are in normal condition.

As soon as sequence switch 100 left position 17, the locking circuit of relay 216

was opened at sequence switch springs 114 and 117. This relay thereupon deenergizes and at its left-hand armature and back contact, closes a circuit for driving sequence switch 200 out of position 16 and into position 18, and at its right-hand armature and back contact connects ground potential from the upper contacts of sequence switch springs 205 to the testing terminal of the trunk with which it is associated for marking this trunk busy to all district selectors having access thereto for preventing seizure of the trunk until the incoming selector and the circuits of the trunk have been restored to normal condition. In position 18, sequence switch 200 closes a circuit for the down-drive magnet 230 which may be traced from grounded battery, through the winding of this magnet and thence to ground at the lower contacts of sequence switch spring 208. Magnet 230, upon energizing, presses a depending portion of the switch shaft against the constantly rotating down-drive roller 4, thereby restoring the switch shaft to its normal position. Upon reaching its normal position, a circuit is established for driving sequence switch 200 out of position 18 and into normal position. This circuit may be traced through the magnet winding of the sequence switch, through the upper left-hand contact of sequence switch spring 206, through the normal segment 231 of the commutator 7, through the brush 225, and thence to ground through the upper right-hand and lower left-hand contacts of sequence switch spring 208. The circuits of the incoming selector trunk are now in normal condition.

Upon leaving position 16, sequence switch 200 opens the circuit extending over the switch brush 223 which has been maintaining relay 314 energized. This relay thereupon deenergizes, closing at its right-hand armature and back contact, a circuit extending through the upper right-hand contact of sequence switch spring 304 for driving sequence switch 300 out of position 16 and into position 18, and at its left-hand armature and back contact, connects ground potential from the upper-contacts of sequence switch spring 303 to the multiple test terminals appertaining to the trunk of the final selector appearing in the banks of all incoming selectors having access thereto for preventing the seizure of this trunk until the circuits of the trunk and the final selector switch have been restored to normal position. In position 18, a circuit is closed for the down-drive magnet 326 of the final selector which may be traced from grounded battery, through this magnet winding, and thence to ground through the lower right-hand and upper left-hand contacts of sequence switch spring 306. The magnet 326, in the usual manner, causes the restoration of the switch shaft which, upon reaching its

normal position, closes a circuit for driving sequence switch 300 out of position 18 and into normal position, which circuit may be traced through the winding of the sequence switch magnet, through the upper contact of sequence switch spring 310, through the normal segment 327 of the commutator 7, through shaft wiper 328 and thence to ground at the upper left-hand contact of sequence switch spring 306. The circuits of the entire system are now restored to normal condition and are in readiness to care for other calls which may be initiated in the exchange.

15 *Line tested and found busy.*

If at the time the final selector switch tested the terminals of the called line, the line had been busy, then the test relay 322 would 20 not have energized but test relay 321 would have energized since this relay energizes on the testing potential found on all busy direct lines and on the last of a group of private branch exchange lines if such last line is 25 busy. When sequence switch 300 leaves position 7 $\frac{1}{2}$, the relay 313 then becomes deenergized closing a circuit at its left-hand armature and back contact for driving the sequence switch out of position 13 and into position 15. As soon as sequence switch 300 leaves position 13, the circuit from the test brush 320, through the windings of test relays 321 and 322 is broken at the lower left-hand contact of sequence switch spring 309 30 and the marginal test relay thereupon deenergizes. When the sequence switch reaches position 15, a circuit is established for the down-drive magnet 326 which may be traced from grounded battery, through the magnet winding 326, through the lower contacts of sequence switch spring 307 (15), through the armature and back contact of relay 321 and thence to ground at the left-hand armature and back contact of test relay 322. The final 40 selector switch is, in the manner previously described, driven into normal position when a circuit is established for driving sequence switch 300 out of position 15 and into position 17, this circuit extending through the magnet winding of the sequence switch, through the upper right-hand contact of sequence switch spring 310, through the normal commutator segment 327 and the shaft wiper 328, and thence to ground at the upper 45 left-hand contact of sequence switch spring 306. In position 17, a circuit is closed at sequence switch contact 312 for connecting a source of busy tone over the circuit established through the brushes of the incoming 50 selector and through the brushes of the district selector and the line finder, to the calling line for the purpose of giving the calling subscriber a busy tone signal. In response to this busy tone, the subscriber restores his 55 receiver to the switchhook and restoration of 60 sequence switch 300 out of position 18 and into normal position, which circuit may be traced through the winding of the sequence switch magnet, through the upper contact of sequence switch spring 310, through the normal segment 327 of the commutator 7, through shaft wiper 328 and thence to ground at the upper left-hand contact of sequence switch spring 306. The circuits of the entire system are now restored to normal condition and are in readiness to care for other calls which may be initiated in the exchange.

70 *Test of a P. B. X. line.*

If a connection had been desired with a subscriber in a private branch exchange and the brushes of the selector switch were positioned on the terminals of the first of a group of lines leading to the private branch exchange and this first line found busy, then neither test relay 321 nor 322 would energize, as the test brush 320 would encounter busy potential on the test contact of such line. When sequence switch 300 now leaves position 7 $\frac{1}{2}$, relay 313 deenergizes but upon reaching position 8 reenergizes over a circuit extending through its winding, through the upper left-hand contact and the lower right-hand contact of sequence switch spring 307, 75 through the armature and back contact of relay 321, and thence to ground through the left-hand armature and back contact of relay 322, and the sequence switch, upon arriving in position 13, finds no circuit completed at 80 the left-hand armature and back contact of relay 313 and comes to rest in position 13. In position 13 a circuit is established through the up-drive magnet 317 which extends 85 through the winding of this magnet, through the lower right-hand contact of sequence switch spring 305, through the front contact and right-hand armature of relay 313, and thence to ground through the upper left-hand contact of sequence switch spring 311. 90 The energization of the up-drive magnet 317 causes the selected brush set 2 to be traversed upwardly. If the next set of bank contacts engaged by the brush set lead to a second busy line of the group leading to the desired 95 private branch exchange, the upward movement of the switch shaft continues. As soon however, as the brushes encounter the terminals of an idle line, the test relays 321 and 322 both energize, opening the initial energizing circuit of relay 313. The relay 313 does not deenergize however, until the switch brushes are properly centered on the 100 set of bank contacts leading to the idle line, since a locking circuit is maintained for the 105 relay 313 which may be traced through its winding, through the upper left-hand contact of sequence switch spring 307, through the lower left-hand contact of sequence switch spring 308, through the commutator 110 segment 329, through the shaft wiper 328, and thence to ground at the upper left-hand contact of sequence switch spring 306. As soon as the switch brushes are properly centered, the shaft wiper 328 engages an insulating portion of the segment 329 and the locking circuit of relay 313 is opened and the relay deenergizes, opening at its right-hand armature and front contact, the circuit of the 115 up-drive magnet 317 and closing, at its left- 120 contact, the circuit of the up-drive magnet 317 and closing, at its left- 125 contact, the circuit of the up-drive magnet 317 and closing, at its left- 130 contact, the circuit of the up-drive magnet 317 and closing, at its left-

hand armature and back contact, a circuit for driving sequence switch 300 into position 15. Since now the test relay 322 is energized, the sequence switch moves into position 16 by 5 reason of the circuit extending through the lower right-hand contact of sequence switch spring 310 to ground at the left-hand armature and front contact of test relay 322. In position 16, busy potential is connected to the 10 test wiper 320 over a circuit extending through the upper left-hand contact of sequence switch spring 309 and to battery through the right-hand winding of the test relay 322.

15 If all of the lines of the group leading to the desired private branch exchange are busy, the final selector would, in the manner above described, move its brushes to the last set of bank contacts of the group of lines, 20 when the test relay 321 becomes energized over the circuit extending through the test brush 320. The test relay 322 does not energize in this circuit because of the busy potential encountered on the test contact of the 25 bank. The final selector switch now functions in the same manner as when a test is made on a busy direct line, the sequence switch 300 moving into position 17 and causing the transmission of a busy tone signal 30 to the calling subscriber.

If the calling subscriber should abandon the call at any time before the selector switches have established a connection with the desired line, the apparatus which has 35 been set up at the time the call is abandoned is automatically restored to normal position. Assuming that the calling line has been extended to the registering mechanism and a portion of the registers have been sent by 40 impulses from the calling dial but no impulses have been sent forward over the fundamental circuit for controlling the selector switches, then sequence switch 600 will be in some position between positions 45 2 and 12. Upon the restoration of the calling subscriber's receiver to its switchhook, relays 613 and 614 of the registering mechanism deenergize, thereby opening the locking circuit of relay 616 which thereupon 50 closes a circuit at its left-hand armature and back contact, extending through the lower left-hand contact of sequence switch spring 612 for driving sequence switch 600 out of 55 any of its positions between 2 and 12 and into position 17, when the registering mechanism and sender become restored to normal in the manner previously described. If at 60 this time, the finder selector FS has been moved from its normal position into contact with the trunk terminals leading to a line 65 finder switch, then this finder selector is restored to normal in the manner previously described, through the deenergization of relay 529, which at its left-hand armature and

back contact closes a circuit extending 65 through sequence switch contacts 511 and 509 for driving sequence switch 500 into position 18, in which position the restoration of the finder selector takes place.

If the extension of the call had progressed 70 to that point where the line finder LF has been started into operation, then upon the abandonment of a call the circuit, which extends through the relay 123 in positions 1 to 11 of sequence switch 100, through the 75 brushes of the switch FS and the wipers of the register selector RS, to ground at the left-hand armature and front contact of relay 616, is opened and relay 123 becomes deenergized. Upon deenergizing, it establishes a circuit through its right-hand armature and back contact for driving sequence switch 100 into position 12. In position 12, a circuit is established for energizing the slow-acting relay 148, which extends from 80 grounded battery, through the winding of this relay to ground at the upper left-hand contact of sequence switch spring 102. This relay, upon energizing, closes a circuit extending from its armature and front contact, through the upper right-hand and lower left-hand contacts of sequence switch spring 103, for reenergizing the relay 123. Relay 123 now closes a circuit at its right-hand armature and front contact for driving 85 sequence switch 100 into position 13. Upon leaving position 12, the circuit of relay 148 is opened, thereby causing its deenergization, and the opening of the circuit through relay 123. Relay 123 now deenergizes and 90 at its right-hand armature and back contact closes a circuit for driving sequence switch 100 into position 16, in which position the line finder switch is restored to normal.

If the call had progressed to such an extent that the district selector or any of the following selector switches had been operated but the final connection with the called subscriber had not been made, then with sequence switch 100 still in position 11, an 105 abandonment of the call causes the sequence switch 100 to be moved out of position 11 and into position 16, as above described, and the restoration of the line finder and any 110 of the switches which have operated proceeds in the manner already described.

115 What is claimed is:

1. In a telephone system, a calling line, selector switches for extending said line, controlling mechanism for controlling the 120 operation of said selector switches, a quick acting finder switch responsive to the initiation of a call on said line for associating said mechanism therewith, means for subsequently associating said mechanism with said line, an impulse circuit established upon the initial association of said mechanism with said line, a second impulse cir- 125

- cuit established upon the subsequent association of said mechanism with said line, means controlled by the calling subscriber for sending impulses over both of said circuits, and means responsive to such impulses for setting said controlling mechanism.
2. In a telephone system, a calling line, selector switches for extending said line, controlling mechanism for controlling the 10 operation of said selector switches, a quick acting finder switch responsive to the initiation of a call on said line for associating said mechanism therewith, a main line finder for subsequently associating said mechanism 15 with said line, an impulse circuit established upon the initial association of said mechanism with said line, a second impulse circuit established upon the subsequent association of said mechanism with said line, means controlled by the calling subscriber for sending impulses over said first circuit while the main line finder is hunting for the calling line and for sending impulses over said second circuit after said line is selected, and 20 means responsive to such impulses for setting said controlling mechanism.
3. In a telephone system, a calling line, selector switches for extending said line, controlling mechanism for controlling the 25 operation of said selector switches, primary and secondary finder switches responsive to the initiation of a call on said line for associating said mechanism therewith, a line finder switch for subsequently associating said mechanism with said line, an impulse circuit established upon the initial association of said mechanism with said line, a second impulse circuit established upon the subsequent association of said mechanism 30 with said line, means controlled by the calling subscriber for sending impulses over said first circuit while said line finder is hunting for the calling line and for sending impulses over said second circuit after said 35 line is selected, and means responsive to such impulses for setting said controlling mechanism.
4. In a telephone system, a calling line, selector switches for extending said line, controlling mechanism for controlling the 40 operation of said selector switches, a link circuit, means responsive to the initiation of a call for connecting said link circuit with said calling line and with said mechanism, a line finder switch for subsequently associating said link with said line, an impulse circuit established upon the initial association of said mechanism with said line, a second impulse circuit established upon the 45 subsequent association of said mechanism with said line, means controlled by the calling subscriber for sending impulses over both of said circuits, and means responsive to such impulses for setting said controlling mechanism.
5. In a telephone system a group of subscriber's lines divided into a plurality of minor and major subgroups, selector switches for extending a calling line of said group, a group of controlling mechanisms for controlling the operation of said selector switches, a link circuit, switching means for connecting said link circuit with an idle one of said mechanisms, a group of primary finder switches for establishing a connection between a calling line and said link circuit, said finder switches having access respectively to said minor subgroups of lines, 50 finder switches having access to said major subgroups for subsequently connecting said calling line with said link circuit, an impulse circuit established upon the initial association of said mechanism with said line, a second impulse circuit established upon the subsequent association of said mechanism with said line, means controlled by the calling subscriber for sending impulses over both of said circuits, and means responsive to such impulses for setting said controlling mechanism.
6. In a telephone system, a group of subscriber's lines divided into a plurality of minor and major subgroups, selector switches for extending a calling line of said group, a group of controlling mechanisms for controlling the operation of said selector switches, a link circuit, switching means for connecting said link circuit with an idle one of said mechanisms, a group of rotary finder switches for establishing a connection between a calling line and said link circuit, said finder switches having access respectively to said minor subgroups of lines, line finder switches for subsequently connecting said calling line with said link circuit, each of said line finder switches being provided with a plurality of brush sets having access 65 respectively to said major subgroups of lines, an impulse circuit established upon the initial association of said mechanism with said line, a second impulse circuit established upon the subsequent association of said mechanism with said line, means controlled by the calling subscriber for sending impulses over both of said circuits, and means responsive to such impulses for setting said controlling mechanism.
7. In a telephone system, a group of subscriber's lines divided into a plurality of minor and major subgroups, a series of selector switches for extending a calling line of said group, a group of controlling mechanisms for controlling the operation of said selector switches, a link circuit, switching means for connecting said link circuit with 70

- 90
- 95
- 100
- 105
- 110
- 115
- 120
- 125

an idle one of said mechanisms, a group of rotary finder switches for establishing a connection between a calling line and said link circuit, said finder switches having access 5 respectively to said minor subgroups of lines, line finder switches paired with the first switches of said series of selector switches, each of said line finder switches being provided with a plurality of brush 10 sets having access respectively to said major subgroups of lines, means individual to said link circuit for connecting said circuit with an idle line finder switch, an impulse circuit established upon the initial association of 15 said mechanism with said line, a second impulse circuit established upon the subsequent association of said mechanism with said line, means controlled by the calling subscriber for sending impulses over both of said circuits, and means responsive to such impulses 20 for setting said controlling mechanism.

8. In a telephone system, a group of subscribers' lines, a series of selector switches for extending a calling line of said group, 25 a group of controlling mechanisms for controlling the operation of said selector switches, a link circuit, switching means for connecting said link circuit with an idle one of said mechanisms, means for establishing 30 a temporary connection between said link circuit and said calling line comprising rotary primary and secondary line finder switches of small capacity, main line finder switches of large capacity paired with the first switches of said series of selector 35 switches, means individual to said link circuit for connecting said circuit with an idle main line finder switch, means for simultaneously starting said switching 40 means and said primary and secondary finder switches upon the initiation of a call, an impulse circuit established upon the initial association of said mechanism with said line, a second impulse circuit established 45 upon the subsequent association of said mechanism with said line, means controlled by the calling subscriber for sending impulses over both of said circuits, and means responsive to such impulses for setting said controlling mechanism.

9. In a telephone system, a group of subscribers' lines, a series of selector switches for extending a calling line of said group, 55 a group of controlling mechanism for controlling the operation of said selector switches, a link circuit, switching means for connecting said link circuit with an idle one of said mechanisms, means for establishing a temporary connection between said link 60 circuit and said calling line comprising rotary primary and secondary line finder switches of small capacity, main line finder switches of large capacity paired with the first switches of said series of selector

switches, means individual to said link circuit for connecting said circuit with an idle main line finder switch, means for simultaneously starting said switching means and said primary and secondary finder switches 65 upon the initiation of a call, an impulse circuit established upon the initial association of said mechanism with said line, a second impulse circuit established upon the subsequent association of said mechanism with said line, means controlled by the calling 70 subscriber for sending impulses over both of said circuits, means responsive to such impulses for setting said controlling mechanism, and means effective upon the establishment of said second impulse circuit for causing the restoration of said primary and secondary finder switches.

10. In a telephone system, a group of subscribers' lines, a series of selector switches for extending a calling line of said group, 85 a group of controlling mechanisms for controlling the operation of said selector switches, a link circuit, switching means for connecting said link circuit with an idle one of said mechanisms, means for establishing 90 a temporary connection between said link circuit and said calling line comprising rotary primary and secondary line finder switches of small capacity, main line finder switches of large capacity paired with the first switches of said series of selector 95 switches, means individual to said link circuit for connecting said circuit with an idle main line finder switch, means for simultaneously starting said switching 100 means and said primary and secondary finder switches upon the initiation of a call, an impulse circuit established upon the initial association of said mechanism with said line, a second impulse circuit established 105 upon the subsequent association of said mechanism with said line, means controlled by the calling subscriber for sending impulses over both of said circuits, means responsive to such impulses for setting said 110 controlling mechanism, means effective upon the establishment of said second impulse circuit for causing restoration of said primary and secondary finder switches, and means effective upon the operation of the 115 selector switches in accordance with the setting of said mechanism for causing the restoration of said switching means and said connecting means.

11. In a telephone system, a calling line, 120 selector switches for extending said line, controlling mechanism for controlling the operation of said selector switches, a quick acting finder switch responsive to the initiation of a call on said line for associating said mechanism therewith, a main line finder for subsequently associating said mechanism with said line, an impulse circuit estab-

- lished upon the initial association of said mechanism with said line, a second impulse circuit established upon the subsequent association of said mechanism with said line,
 5 means controlled by the calling subscriber for sending impulses over said first circuit while the main line finder is hunting for the calling line and for sending impulses over said second circuit after said line is selected,
 10 means responsive to such impulses for setting said mechanism, and means effective upon the establishment of said second impulse circuit for opening said first impulse circuit.
 15 12. In a telephone system, a calling line, selector switches for extending said line, controlling mechanism for controlling the operation of said selector switches, a quick acting finder switch responsive to the initiation of a call on said line for associating said mechanism therewith, a main line finder for subsequently associating said mechanism with said line, an impulse circuit established upon the initial association of said mechanism with said line, a second impulse circuit established upon the subsequent association of said mechanism with said line, means controlled by the calling subscriber for sending impulses over said first circuit
 20 while the main line finder is hunting for the calling line and for sending impulses over said second circuit after said line is selected, means responsive to such impulses for setting said mechanism, means effective upon the establishment of said second impulse circuit for opening said first impulse circuit, and means effective upon the operation of the selector switches in accordance with the setting of said mechanism for opening said
 25 second impulse circuit.
 30 13. In a telephone system, a calling line, a directively controlled switch for extending said line, a plurality of nondirectively controlled line extending switches, a plurality of relays for controlling the operation of said last named switches, and means whereby a varying number of said relays
 35
 40
 45

are utilized for controlling said first named switch.

14. In a telephone system, a group of subscribers' lines divided into a plurality of subgroups, means for extending a calling line comprising a line finder switch provided with a plurality of brush sets having access respectively to said subgroups of lines, a plurality of nondirectively controlled switches for establishing a preliminary extension of said calling line, a plurality of relays for controlling the operation of said non-directive switches, and means made effective by said preliminary extension for controlling the selection of a brush set of said finder switch through the employment of one or more said relays.

15. In a telephone system, a group of subscribers' lines divided into a plurality of subgroups, means for extending a calling line of said group comprising a line finder switch provided with a plurality of brush sets having access respectively to said subgroups of lines, means for controlling the extension of the calling line, a link circuit, means individual to the link circuit for connecting said controlling means therewith, means comprising a preliminary finder switch having access to a subgroup of said lines and a secondary finder switch individual to said link circuit for connecting said link circuit with said calling line, a plurality of relays associated with said link circuit for controlling the operation of said switch individual thereto, and circuits associated with said link circuit and made effective in accordance with the particular subgroup of lines which is connected to said link circuit for controlling the brush selection of said first mentioned line finder through the employment of a varying number of said relays.

In witness whereof, I hereunto subscribe my name this 4th day of December A. D., 1919.

SAMUEL B. WILLIAMS, JR.
